UNITED STATES PATENT OFFICE.

DAVID B. WHISTLER AND CHARLES W. RIPSCH, OF DAYTON, OHIO, ASSIGNEES TO THE RECORDING AND COMPUTING MACHINES COMPANY, OF DAYTON, OHIO, A CORPORATION OF OHIO.

RECORDING AND COMPUTING MACHINE.

1,132,234.

Specification of Letters Patent.

Patented Mar. 16, 1915.

Application filed June 29, 1912. Serial No. 706,576.

To all whom it may concern:

Be it known that we, DAVID B. WHISTLER and CHARLES W. RIPSCH, citizens of the United States, residing at Dayton, in the 5 county of Montgomery and State of Ohio, have invented certain new and useful Improvements in Recording and Computing Machines, of which the following is a specification, reference being had therein to the 10 accompanying drawing.

This invention relates to recording and computing machines, is designed more particularly for use with a fare register and is an improvement upon the machine shown 15 and described in Patent No. 990,666, granted April 25th, 1911, to W. I. Ohmer, D. B. Whistler and J. E. McAllister.

One object of the present invention is to produce a machine of this character which 20 will be simple and compact in construction and can be manufactured at a relatively low cost.

To this end it is also an object of the invention to provide mechanism for making 25 three separate records of the fares received, or other items of business transacted, each item being computed on separate sets of counting devices and the three records being printed by a single set of printing counters.

30 A further object of the invention is to provide the machine with a system of locks to control the movements of the several operating parts which will be simple and durable in construction and positive in their operation.

The mechanism of the above-mentioned 35 patent comprises two groups of printing counters adapted to preserve records, respectively, of a single trip and of a plurality of trips and means are provided for printing a record from either of said groups of counters. In connection with these two groups of counters there is an accumulator, comprising a group of non-printing counters, 40 which are actuated in unison with the two groups of printing counters to cause the same item to be registered thereon, that is, registered on the printing counters, thus 45 preserving a third record which, being independent of the other records, may be made 50 to cover a longer period of time than either of the other records. In order to take a

record from the non-printing counters the count is first transferred to one of the groups 55 of printing counters, which have previously been reset to zero, and then printed from said group of printing counters. This mechanism involved many parts and constituted a large machine. In order to reduce the size 60 of the machine, eliminate as many of the parts as possible and reduce the cost of production we, have, in the present machine, eliminated one group of printing counters and have substituted therefor a second 65 group of non-printing counters. The two groups of non-printing counters are so mounted as to be actuated simultaneously with the printing counters and each group of non-printing counters is adapted to transfer its record to the single group of printing counters, the transfers being made separately so that a record of each can be printed and preserved. Further, the transfers are 70 made in a predetermined order so that the 75 record from one counter must be transferred and printed before the record from the other counter is transferred and printed. These changes have resulted in reducing the size 80 of the machine to approximately two-thirds its former size and to a corresponding reduction in the number of parts and cost and has also materially simplified the mechanism. In connection with the single group 85 of printing counters we have so modified the printing mechanism that the records from the three groups of counters are printed by moving the platen in a single direction, the trip and total records being printed by 90 movements of different lengths. Also in connection with these counters we have provided devices or locks for controlling the movements of the several parts to prevent 95 their inadvertent operation or their operation in such a manner as to garble the records or to cause the records to be taken in the wrong sequence. The whole results in a very compact machine comprising a 100 comparatively few parts and these parts being of such a character and so arranged as to be strong and durable and not easily disarranged or broken, a condition highly desirable in a machine designed for street car service.

In the accompanying drawings, Figure 1 105 is a front elevation of a machine embody-

ing our invention showing the casing in section; Fig. 2 is a rear elevation of the same, also showing the casing in section; Fig. 3 is an elevation of the right hand end of the 5 machine, as the observer faces the same; Fig. 4 is an elevation of the left hand end of the machine; Fig. 5 is a vertical section taken on the line $x-x$ of Fig. 1 and looking in the direction of the arrows; Fig. 6 is a 10 vertical section of a portion of the machine showing the printing counters, the actuator therefor and the setting mechanism for the actuator; Fig. 7 is a detail view of the counters carried by the several counter 15 shafts and their actuators showing the several sets of counters as drawn apart; Fig. 8 is a detail of the indicators and their operating mechanism showing the parts separated; Fig. 9 is a sectional view taken on 20 the line $y-y$ of Fig. 8 and looking in the direction of the arrows, showing the driving and transfer mechanism for the passenger indicator; Fig. 10 is a detail view of the escapement, forming a part of the transfer 25 mechanism, and the resetting device for the passenger indicator; Fig. 11 is a sectional view showing in detail the resetting shaft; Fig. 11^a is a detail of a portion of the resetting shaft showing the actuating cam in 30 section; Fig. 12 is a sectional view showing the connection between the platen shaft and the cam plate which controls the printing mechanism; Fig. 13 is a sectional view taken on the line $z-z$ of Fig. 1 and looking in the 35 direction of the arrows, showing the locking device to hold the accumulators normally out of mesh with the printing counters; Fig. 14 is an end view of the key-controlled lock for the machine; Fig. 15 is a side elevation 40 of the same; Fig. 16 is a detail view of the key barrel for this lock; Fig. 17 is a sectional view of the key barrel; Fig. 18 is a detail view of the key; Fig. 19 is a detail of the type plate carrying the car number; Fig. 20 is a detail of the driving gears for the "in" and "out" indicator; Fig. 21 is a detail view of the gearing connecting the actuator shaft for the "in" and "out" indicator with the resetting shaft for the 45 passenger indicator; Fig. 22 is an elevation of the same; Fig. 23 is an elevation of the operating device for the actuating shaft of the register, looking from the frame member toward the end of the machine; Fig. 24 is a 50 plan view of the same; Figs. 25, 26, 27 and 28 are detail views showing successive positions of the operating device shown in Fig. 23; Figs. 29 and 30 are detail views of the locking devices for controlling the direction 55 of movement of the printing mechanism; Fig. 31 is a detail view of the driving segment for the printing mechanism; Fig. 32 is an elevation of the printing handle and the devices connecting the same with the 60 printing shaft; Fig. 33 is a sectional view 65 taken on the line $w-w$ of Fig. 6 and looking in the direction of the arrows, showing the locking mechanism for controlling the movement of the accumulators into operative relation with the printing counters; Fig. 34 is a detail view of the actuating device for the several counters, together with the ratchet mechanisms for controlling the direction of movement of the accumulator shafts; Fig. 35 is a detail view of the actuating 70 gears for the locking disks for controlling the movement of the printing mechanism; Figs. 36 and 37 are detail views of the two disks controlling the direction of movement of the printing mechanism; Fig. 38 is a detail view of the gearing actuated by the resetting of the conductor's accumulator shaft for shifting the locking disks; Fig. 39 is a detail of the alining and detent device for the locking disks; Fig. 40 is a 75 detail view of the locking device to hold the inspector's accumulator normally out of operative relation with the printing counters; Fig. 41 is a detail of the locking mechanism actuated from the printing shaft for holding the various mechanisms against movement during the printing operation; Fig. 42 is a detail of the locking mechanism to prevent more than one record being 80 printed; Fig. 43 is a detail view of the locking mechanism to hold the printing mechanism against movement while the printing counters are being reset to zero; Fig. 44 is a detail view of the locking device for the operating handle and the indicator; Fig. 45 is a 85 detail view of the device for preventing the overthrow of the indicator shaft upon its resetting movement; Fig. 46 is a rear elevation of the controlling disks and their co-operating devices for the printing mechanism; Fig. 47 is a sectional view showing the manner of retaining the type plate carrying the car number; Fig. 48 is a development of the cam for controlling the actuator for the total cash counters; Fig. 49 is a 90 development of the cam for controlling the fare counters; Fig. 50 is a development of the cam for controlling the trip passenger-counters; and Fig. 51 is a facsimile of a 95 printed record, the same being broken into several parts and including several trip records, two conductors' records and an inspector's record.

In these drawings we have illustrated one embodiment of our invention and have 100 shown the same as applied to street car fare registers. As is common in machines of this type the active parts of the mechanism are mounted upon a main frame comprising end members 1 and 2 connected one to the other and spaced apart by means of tie bars, such as are shown at 3, 4 and 5. The mechanism as a whole is inclosed in a casing or cabinet 6 of any suitable design. This 105 cabinet forms no part of the invention and

need not be described here further than to state that it is provided with the necessary sight openings for the visual indicators and with openings through which keys or other operating devices may be inserted to actuate the several parts of the mechanism, as will hereinafter appear. When this casing is locked upon the machine no access can be had to the mechanism thereof save only in the prescribed manner. The machine may be supported in any suitable manner but, as here shown, the frame is provided with lugs 7 by means of which it may be attached to a vertical supporting member, such as the wall of a street car.

Mounted on the frame of the machine are a plurality of counting devices adapted to record the fares received or other items relating to a business transaction. Preferably these counting devices are of such a character that a record may be taken from the same and preserved. The present machine is adapted to handle five classes of fares, namely, 5¢ and 3¢ cash fares, tickets, 5¢ transfers and transfers, and there is a separate counting device for each class of fares, as indicated at 8, 9, 10, 11 and 12, respectively. In addition to the specific fare counting devices there is a total cash counting device 13 adapted to compute and record the total amount of cash represented by the 5¢ and 3¢ fares and the 5¢ transfer recorded by the specific fare counters 8, 9 and 11, respectively. There is also a total passenger counting device 14 which records every fare received and thus indicates the total number of passengers carried. Preferably, the counting devices above mentioned are adapted to record the transactions for a given period of time, such as one trip of a street car, and are designed to be reset to zero at the end of that period and a new record made for the succeeding period. In addition to the trip counting devices the machine is provided with a grand total passenger counter or machine total counting device, as indicated at 15. This counting device is never reset to zero and indicates the total number of fares registered since the machine was installed.

The counting devices may be of any suitable character but in the present instance we have shown each counting device as comprising a group of printing counters, each printing counter consisting of a type wheel 16 and a gear 17 secured to and rotating with the type wheel. The units counter wheel of each group of counters is positively actuated by means of an actuating device hereinafter to be described and the count is transferred from the units counter wheel to the tens counter wheel and from the tens counter wheel to the hundreds counter wheel, etc., by transfer mechanism of any suitable character. In the present machine we have

employed a well known transfer mechanism comprising a series of transfer gears 18 and spring pressed pawls 19 engaging between the teeth of the transfer gears to aline the type wheels and to hold the same against accidental displacement. These counting devices may be reset to zero by any suitable mechanism. In that form of the device here shown the several groups of printing counters are mounted on a shaft 20 journaled at one end in the frame member 1. In this machine, however, that end of the shaft adjacent to the frame member 2 is not mounted directly thereon, but is journaled in an arm 5^a, (see Fig. 46), carried by the tie bar 5 and is provided with an axial recess 21 to receive the end of a short shaft 22, which is journaled in the frame member 2. This arrangement permits the shafts 20 and 22 to have independent rotary movement but maintains the same in axial alinement.

The shaft 20 is of the type known as a resetting shaft and to this end is provided with a plurality of annular grooves 23, Fig. 11, which grooves correspond in number and arrangement to the several groups of printing counters mounted on the shaft and are adapted to receive projections or pins 24 carried by the respective counter wheels. The shaft 20 is also provided with a longitudinal slot 25 in which is mounted a key 26 having in its outer edge a series of notches 27 corresponding in number, arrangement and size with the annular grooves in the shaft. When the key 26 is in its normal position the notches therein will register with the annular grooves in the shaft and the counter wheels will be free to rotate upon the shaft. When it is desired to reset the counter to zero the key 26 is moved out of its normal position and into such a position that solid portions of the key will extend across the several annular grooves, and, when rotary movement is imparted to the shaft, these portions of the key will engage the pins on the respective counter wheels and will cause the counter wheels to rotate with the shaft. The pins are secured to the several counter wheels in the same positions relatively to the numerals on the periphery of those wheels and, consequently, when all the pins are in engagement with the key the corresponding numerals on the wheels will be in longitudinal alinement and when the shaft makes a complete revolution the type wheels will be reset to zero. So much of the resetting mechanism is well known and does not form a part of the present invention. In the use of this mechanism, however, it has been customary to impart longitudinal movement to the key 26 to move the notches therein into and out of registration with the annular grooves in the shaft by means of two cam wheels, one arranged at each end of the

shaft and held against rotatory movement. While such an arrangement is in the main satisfactory it presents certain difficulties. One is the difficulty encountered in assembling the machine, as it is necessary that these cams be arranged in exact alinement. Otherwise the key will be locked and not shifted by the cams. Moreover, the distance between the end members of the frame varies in different machines and this variation, although very slight, is sufficient to affect the action of the cams, and makes it necessary to adjust the cams longitudinally of the shaft when the machine is assembled. To overcome the objections to the arrangement of the cams at opposite ends of the key we have provided a single cam disk, which is indicated at 28, Fig. 11, and has its opposite sides provided with cam surfaces. The cam surface on one side of the disk comprises a tapered recess 30 and that on the other side comprises a tapered projection 31 corresponding in size and shape to the recess 30. The projection and recess are arranged on opposite sides of the disk 28 with their centers in longitudinal alinement. The disk 28 is mounted on a fixed part of the machine, preferably one of the end members of the frame thereof, and extends about the resetting shaft 20. That portion of the key 26 which extends through the disk 28 is provided with a portion having a recess 32, the edges of which extend on opposite sides of the cam disk 28 and are spaced apart a distance substantially equal to the thickness of the disk. Consequently, the rotation of the shaft will cause the recessed portion of the key to travel about the cam surface and longitudinal movement will be imparted to the key. Inasmuch as the recess and projection are formed in the cam itself and are both at the same end of the shaft there is no difficulty encountered in assembling these parts in the machine nor can they be thrown out of alinement in the use of the machine. The resetting shaft 20 may be rotated by any suitable means but preferably has one end squared to receive an actuating key or socket wrench.

The several counting devices may be actuated in any suitable manner to cause the same to record the respective items or fares. Preferably, a single actuating member is provided for actuating the several specific fare counting devices and in that form of the device here shown this actuator comprises a toothed actuating member 33 which is mounted to slide upon and rotate with an actuator shaft 34 journaled at its opposite ends in the frame members 1 and 2. As shown, the actuating member 33 is in the form of a two-toothed gear, whereby each half revolution of the supporting shaft will cause the actuator to engage and operate that counter with which it is in operative

relation. Means are provided operable by the conductor, or other operator, at a point more or less remote from the machine to move the actuator 33 into operative relation with that group of printing counters adapted to record the fare received or the item of business transacted. This is accomplished in the present machine by means of a carrier 35 slidably mounted upon a shaft 36, mounted in the end members 1 and 2 of the main frame, and having a forked arm 37 adapted to engage a grooved collar 38 secured to the actuator 33, thus causing the actuator to move with the carrier but permitting the actuator to rotate with the shaft 34. The carrier 35 is also provided with a projection 39, preferably provided with an antifriction roller, adapted to enter the groove of a cam 40 which is mounted upon and rotatable with a shaft 41 journaled in the end members of the main frame and adapted to have connected to either end thereof suitable mechanism for rotating the same from the conductor's or collector's station. The contour of the groove of the cam 40, which is shown in detail in Fig. 49, is such that the rotation of the setting shaft 41 will cause the actuator 33 to move successively into operative relation with the several specific fare counting devices. One end of the cam groove extends slightly beyond the last operative position of the actuator, which position, in the present instance, is the ticket position. The rotation of the setting shaft 41 beyond the ticket position will, therefore, move the actuator beyond its operative position with relation to the ticket counting device and into a neutral position.

The total cash counting device is here shown as comprising a group of printing counters similar to the counters of the specific fare counting devices except that the units counter wheel is provided with two driving gears 42 and 43 spaced some distance apart and connected by means of a sleeve. (See Figs. 6 and 7.) This units counter is actuated each time one of the cash fare counting devices is actuated and further the units counter of the total cash counting device is moved through a number of units corresponding to the amount of the fare received, that is, either through three units or five units. This is preferably accomplished by slidably mounting on the shaft 34 two actuators 44 and 45, each provided on the opposite sides of its center with two groups of teeth. In the actuator 44 there are five teeth in each group and in the actuator 45 there are three teeth in each group. The normal position of these actuators is between the two driving gears 42 and 43 of the units counter wheel and when moved in one direction the actuator 44 will be moved into operative relation with the gear 42 and a

half revolution of the shaft 34 will cause the units counter to be advanced five units. When the actuators are moved in the opposite direction the actuator 45 will be moved 5 into operative relation with the gear 43 and a half revolution of the shaft 34 will cause the units counter to be advanced three units. The actuators 44 and 45, which are preferably rigidly secured one to the other and rotate in unison, are actuated by a carrier 46 similar to the carrier 35 and having a forked arm adapted to engage a grooved collar 47 rigidly secured to the two actuators. The carrier also has a projection 48 extending 10 into the groove of a cam 49 which is rigidly secured to the setting shaft 41 and is of such shape that when the actuator 33 is in operative relation with either the transfer or ticket counting devices, or is in its neutral 15 position, the two actuators 44 and 45 will be in a neutral position between the gears 42 and 43 of the units counter wheel and when the actuator 33 is moved into operative relation with either the 5¢ cash fare counting 20 devices or the 5¢ transfer counting devices the corresponding actuator 44 will be moved into operative relation with the gear 42 of the units cash counter wheel. When the actuator 33 is moved into operative relation 25 with the 3¢ cash fare counting devices the actuator 45 will be moved into operative relation with the gear 43 of the units cash counter wheel. In this connection it may be noted that a 5¢ transfer is issued upon the 30 payment of 5¢ in cash. The fare is recorded as a 5¢ transfer but the cash is added to the total cash counters.

The trip total passenger counter 14 is also actuated by a two toothed counter wheel, 50, 40 mounted on and rotatable with the shaft 34. This actuator is normally stationary with relation to the shaft 34 but is capable of longitudinal movement on the shaft to cause it to assume a neutral position, that is, a position not in operative relation to the counting device. To this end a carrier 51 is mounted on the shaft 36 and provided with a forked arm to engage a grooved collar 52 of the actuator 50 and is also provided with 45 a projection 53 to enter the groove of a cam 54 mounted on the setting shaft 41. This cam groove is straight save for an off-set portion at one end, which offset portion is sufficient to move the actuator 50 out of operative relation with the gear of the units counter wheel when the cam is moved past the ticket position.

Any suitable mechanism may be employed 60 for operating the actuator shaft 34 to move the actuators through a half revolution and cause the particular fare received to be recorded. This movement is usually imparted to the shaft by means of operating mechanism mounted in the car and in the most approved forms of this mechanism the op-

erating member is given a double movement upon each operation of the machine, that is, it is moved out and back, this movement being usually in the form of an oscillating movement. In the present machine we have, 70 therefore, provided operating devices of such a character that this double movement of the operating member or handle will impart two part revolutions to the shaft 34 both in the same direction and the sum of 75 the two being equal to a half revolution of that shaft. This operating device, as here shown, (see Figs. 3 and 23 to 28) comprises two intermeshing gears 55 and 56, the gear 55 being mounted on that portion of the 80 shaft 34 which projects beyond the frame member 2 and the gear 56 being mounted on a stud 57 mounted in said frame member. Mounted on the shaft and the stud, respectively, are also two mutilated gears 85 58 and 59. These gears are here shown as arranged in substantially the same plane and each has two sets of teeth arranged on opposite sides thereof. As here shown the two groups of teeth of each mutilated gear are 90 arranged on diametrically opposite sides of the gear and the diameters, of the two gears, on which the respective teeth are mounted are arranged at an angle one to the other so that the rotation of the gears will not at any 95 time bring their teeth into engagement but the teeth of one gear will pass through the space between the two groups of teeth of the other gear. Mounted upon the frame of the machine is a rack which is adapted to mesh, 100 when moved in one direction, with the teeth of one of said mutilated gears, and, when moved in the opposite direction, with the teeth of the other of said mutilated gears. The mutilated gears being rigidly secured to 105 the full gears 55 and 56 it will be obvious that when the mutilated gear 58 is engaged by the rack the shaft 34 will be rotated through a partial revolution and when the mutilated gear 59 is engaged by the rack, 110 when the rack is moving in the opposite direction, the gear 56 will be rotated and will transmit movement to the gear 55, thus imparting a further rotation to the shaft 34 115 in the same direction in which it was moved when the rack engaged the gear 55. In the present arrangement of the device this rack is a segmental rack, as shown at 60, and is rigidly secured to a shaft 61 mounted in the frame of the machine and adapted to have 120 an operating mechanism connected therewith. Suitable devices are provided to prevent the overthrow of the mutilated gears and further to provide proper clearance for the segmental rack upon its return movement. To this end the shaft 34 and stud 57 have mounted thereon and rigidly secured to the respective gears disks 62 and 63 each having in its opposite sides inwardly curved recesses. Mounted on the shaft 61 and mov- 125 130

ing with the segmental rack 60 are two plates 64 and 65 having curved outer edges adapted to enter the recesses of the disks 62 and 63, respectively. The arrangement of the disks 5 and the plates is such that the plate 64 will enter the recess in the disk 62 just as the segmental rack clears the mutilated gear 58. Consequently, this gear, to which the disk 10 is secured, will be locked against further movement and its overthrow prevented. Further, the shapes and arrangement of the disks and the coöperating plates are such that the forward edge of the plate will engage the curved edge of the disk just as the segmental rack clears the last tooth of the segmental gear and will impart a slight further movement to the disk and, consequently, to the mutilated gear. This further movement carries the last tooth of the mutilated gear 15 away from the segmental rack and affords ample clearance for the return movement of the segmental rack. Of course, when the segmental rack passes out of engagement with the teeth of the mutilated gear there will be a slight clearance between these 20 parts, which, if the parts remain absolutely in the same relation, will afford sufficient clearance for the return movement of the segmental rack, but this clearance is so slight 25 that a very small movement of the mutilated gear would cause the same to project into the path of the teeth of the segmental rack upon its return movement and thus interfere with the operation of the mechanism 30 and probably jam the same in a serious manner. With the present device such clearance is provided that no ordinary shock or jar can impart sufficient movement to the mutilated gear to cause the same to interfere 35 with the operation of the segmental rack. The operation of the recessed disk 63 on the stud 57 and the plate 65 on the shaft 61 are identical with the operation just described and it will be apparent that a rocking movement 40 imparted to the shaft 61 will cause the shaft 34 to receive two forward movements of approximately ninety degrees each. Further, it will be apparent that the device is effectively locked against overthrow at the 45 end of both movements and that ample clearance is provided to permit the proper relative movements of the parts.

Mounted on the shaft 61 and rigidly secured to the segmental rack is a full stroke 50 mechanism to make it necessary for the operator to move the shaft 61 in each direction through a distance sufficient to impart a full quarter revolution to the shaft 34. This means, as here shown, comprises a segmental plate 66 having a series of teeth in the edge thereof adapted to be engaged by a pawl 67 mounted on the frame member 2 adjacent to the periphery of the plate 66 and held normally in a central position by a 55 spring 68. The teeth project some distance

beyond the adjacent portions of the edge of the disk and when the disk is at either extreme of its movement the pawl can assume a central position, as shown in Fig. 3, but when the plate 66 is moved to cause the 70 teeth to engage the pawl it will be forced away from its central position and caused to ride over the teeth and engage the same in a manner that will prevent any rearward movement of the plate and operating mechanism until the pawl has passed beyond the 75 end of the teeth when it will again assume a central position and retain the same until it is again engaged by the teeth and caused to ride over the same. It will be noted that 80 this arrangement of the mechanism requires that the movement be of a sufficient length to operate the actuator but does not further limit the movement which may be imparted to the operating mechanism. This is important 85 because the throw of the operating mechanism varies in different installations and even in the same installation there will be some variation in this throw under different conditions and where the movement of 90 the operating mechanism is positively limited it will sometimes jam so as to seriously interfere with its operation.

In order that the counting devices may be properly actuated it is necessary that the actuator should be in correct alignment therewith. To insure that the actuators will be in proper alignment with their respective counting devices means are provided which are actuated by the operating mechanism to 95 position the actuators. To this end a star wheel 69 is rigidly secured to the end of the setting shaft 41. (See Figs. 3 and 6.) This star wheel is provided with five teeth arranged to provide five V-shaped spaces, one 100 corresponding to each operative position of the actuator for the specific fare counting devices. A pawl 70 is pivotally supported on the frame member of the machine adjacent to the star wheel and has a tapered nose 71 adapted to enter the V-shaped spaces in the star wheel. The arrangement of the star wheel and the pawl is such that when the nose of the pawl is in the apex of any one of the V-shaped spaces the actuator 33 105 will be in proper operative relation with some one of the specific fare counting devices. Rigidly secured to the segmental rack 60, and forming a part of the operating mechanism, is a plate arranged in the same plane 110 with the pawl 70 and adapted to engage the pawl and move the same toward the star wheel 69 at the beginning of the movement of the operating mechanism. In the present instance this plate is a continuation of the plate 66, which forms a part of the full stroke mechanism, and has its forward edge cut away adjacent to the pawl 70 so that normally the adjacent edge of the pawl will 115 enter the cut away portion of the plate and 120

125 normally the adjacent edge of the pawl will enter the cut away portion of the plate and 130

the nose of the pawl will lie out of the path of the star wheel and the setting mechanism will be free to rotate. The first portion of the movement of the operating mechanism 5 will cause the edge of the plate 66 to engage the adjacent edge of the pawl and move the same toward the star wheel, thus causing the nose of the pawl to enter one of the V-shaped spaces of the star wheel and 10 aline the actuator 33. So long as the operating mechanism is in action, that is, so long as it is out of its normal or idle position, the adjacent edge of the pawl will rest upon the segmental surface of the plate 66 and the 15 pawl will be held in engagement with the star wheel, thus locking the star wheel and the setting shaft 41 against movement during the operation of the recording devices. That tooth, 69^a, of the star wheel lying just 20 beyond the space corresponding to the ticket position of the actuator has a segmental edge which is adapted to engage the nose of the pawl and hold the same in the path of the plate 66 when the actuator has been 25 moved into its neutral position. With the pawl in this position the operating mechanism will be locked against movement. It will be noted in this connection that any effort to impart movement to the operating 30 mechanism will cause the plate to engage the inclined end of the pawl and that a large portion of the thrust thereon will be exerted upon the stud by means of which the pawl is connected to the frame of the machine and but a small amount of the thrust 35 will be imposed upon the setting shaft.

It is also desirable that the machine should be normally locked against operation in order that only authorized persons may 40 operate the same. To this end we have provided a locking device for the operating mechanism which can be released only by a key which is entrusted to the conductor or other authorized officer. Various locking 45 mechanisms may be employed for this purpose but that here shown is very simple in its construction and affords a very positive lock and one that can not well be released by unauthorized persons. (See Figs. 3, 14, 15, 50 16, 17 and 18.) This lock comprises a key barrel 72 mounted in the frame of the machine and arranged in alinement with an opening in the cabinet. The inner end of the key barrel extends inward some distance beyond the side member of the frame 55 in which it is mounted. Pivotaly mounted on a stud 73 carried by the side member 2 of the frame is an arm 74 arranged to be moved into and out of the path of segmental plate 75 rigidly secured to the segmental rack 60 and forming a part of the operating mechanism. The relative positions of the arm 74 and the plate 75 are such that when the former is in the path of 60 the latter the operating mechanism will be

locked against movement. The stud 73 on which the arm 74 is pivotally mounted is arranged near the key barrel 72 and the hub of the arm 74 has secured thereto a finger 76 extending transversely to the key barrel 70 and adapted to enter a transverse slot 77 formed in the key barrel. Pivotally mounted on a second stud 78 also arranged adjacent to the key barrel is a second arm 79 having its outer end arranged to be moved 75 into and out of the path of a projection or pin 80 secured to the arm 74. A spring 81 tends to hold the arm 79 in engagement with the projection 80 and when it is in this position the arm 74 will be held against movement out of the path of the plate 75. Rigidly secured to the arm 79 and extending transversely to the key barrel 72 is a finger 82 which enters a second transverse slot 83 80 formed in the key barrel beyond the transverse slot 77, that is, in such a position that the transverse slot 77 will lie between the second slot 83 and the outer end of the key barrel. To unlock the machine it is necessary first that the arm 79 be moved to 85 release the arm 74 and then that the arm 74 be moved out of the path of the plate 75. To accomplish this each conductor and authorized officer is provided with a key 84 which is of such a shape as to fit within 90 the key barrel and is provided on its lower edge with a type plate 85 carrying the identifying number of the conductor or other officer. The key barrel is provided at its lower edge with a longitudinal slot 86 to 95 permit the passage of this type plate and when the key is in a position which will unlock the operating mechanism the type plate 85 will be in a position to print on the record the number of the officer to whom the key has been issued. Each key is provided with two longitudinal grooves 87 and 100 88 each extending from the inner end of the key, that is, the end which enters the key barrel, to a point some distance remote 105 from the inner end of the key, at which point the grooves taper out to the surface of the key. The groove 87 is somewhat longer than the groove 88. When the key is inserted in the key barrel the two grooves 110 will be in a position to receive those portions of the arms 76 and 82 which extend through the respective slots into the key barrel. The groove 88 in the key which receives the innermost finger, 82, is, as stated, 115 somewhat shorter than the other groove and the tapered end of this groove will engage the finger 82 and force the same out of the slot 83 in the key barrel before the tapered end of the groove 87 engages the finger 76. 120 As a result the arm 79 will be moved out of the path of the projection on the arm 74 before any effort is made to move the arm 74 out of the path of the plate 75, which latter movement will result from the further 125 130

inward movement of the key. The lock is a very simple and strong one and by the arrangement of the tripping mechanism it cannot be released by any device other than the key or something very similar to the key. A lead pencil or pointed rod cannot be inserted in the barrel and the mechanism released because such a device would first engage the finger 76 which is positively locked 10 against movement.

The machine is also provided with visual indicators to indicate to the passengers, as well as to the conductor, the character of the fare recorded, the total number of fares 15 of all kinds received on that trip and the direction of movement of the car, that is, "in" or "out". (See Figs. 1, 3, 8, 9, 10, 20, 21 and 22.) To this end an indicator shaft 89 is journaled in the side members 20 1 and 2 of the main frame substantially parallel with the setting shaft 41 and has mounted thereon an indicator 90 which bears on its surface indications corresponding to the fares which the machine is adapted to 25 register. This indicator is geared directly to the setting shaft by means of intermeshing gears 91 and 92 rigidly secured respectively to the indicator and the setting shafts. The indicator is so arranged with reference 30 to the setting shaft that that indication which corresponds with the fare which the machine is set to record will be visible through the sight opening. The passenger indicator comprises three indicator wheels 35 93 loosely mounted on the shaft 89 and each bearing on its periphery the figures 0 to 9, inclusive. These indicator wheels are driven from the operating mechanism for recording the fare and consequently the unit indicator wheel is advanced one space for each 40 operation of the machine. To accomplish this the first indicator wheel has rigidly secured thereto a driving gear 94, the teeth of which are wide and have their outer ends 45 concave. As here shown this gear is mounted on the outside of the frame member 2 and is connected with the indicator wheel by means of a sleeve 95 extending through the frame member about the shaft 50 89. The gear 94 is driven by a two-toothed driver or actuator gear 96 which is mounted on the stud 57 and rigidly secured to the gear 56 so that it is caused to rotate in unison with those parts of the operating mechanism 55 which are carried by the stud 57. The teeth of the gear 96 are arranged on diametrically opposite sides thereof and the gear preferably has a portion of the surface between the teeth on both sides thereof convex and arranged to engage the concave surface 60 of the adjacent tooth as the gear 96 is rotated to actuate the gear 94, thereby checking the rotary movement of the gear 94 and preventing its overthrow. The body 65 portion of the gear 96 is cut away imme-

dately in front of each tooth for a distance slightly greater than the width of the teeth of the gear 94 and when the gear 96 is in its idle position the adjacent tooth of the gear 94 will be opposite this cut away portion of 70 the gear 96, thus leaving the gear 94 free to turn to zero.

The count is transferred from the units counter wheel to the tens counter wheel and from the tens counter wheel to the hundreds 75 counter wheel by means of well known transfer mechanism comprising a one-toothed gear 97 acting through transfer pinions 98 on a shaft 99 to actuate a gear 100 secured to the adjacent counter wheel. 80 Spring-held alining pawls 101 are mounted on a shaft 102 and have V-shaped ends to engage between the teeth of the respective gears 100 and center the same with the indication in proper relation to the sight opening. 85 The devices for preventing the overthrow of the tens and hundreds counter wheels each comprises an escapement wheel 103 secured to the respective counter wheel and a double-nosed escapement pawl 104 90 pivotally mounted adjacent to said escapement wheel and having one nose, 105, held normally in engagement with the escapement wheel by means of a spring 106. When the nose 105 is in engagement with 95 the escapement wheel the other nose, 107, will be in position to clear the teeth of the escapement wheel. As the escapement wheel rotates the tooth adjacent to the nose 105 will engage the under side of that nose of 100 the pawl, raise the same and move the nose 107 into the path of the tooth which is then approaching the same. (See Figs. 20, 21 and 22.) The tooth which is in engagement with the nose 105 of the pawl will clear the same 105 an instant prior to the engagement of the pawl 107 by the tooth which is approaching the same and the spring 106 is of such tension that the nose 107 will not be lifted in time to clear this tooth but will be engaged 110 by the tooth and check the movement of the escapement wheel and, consequently, of the counter wheel. As soon as the movement of the escapement wheel has been checked and there is no longer any pressure against the 115 end of the nose the spring will withdraw the same and move the nose 105 again into engagement with the escapement wheel.

The passenger counters 93 may be reset to zero in any suitable manner. In the present instance each counter wheel has pivotally mounted thereon a spring-pressed pawl 108 adapted to engage a longitudinal groove 109 in the indicator shaft 89. Thus, the rotation of this shaft will cause each pawl 125 108 and its counter wheel to be picked up by the shaft and moved to zero position. The indicator shaft is adapted to have the resetting movement imparted thereto independently of the resetting of the printing 130

counters, although obviously the two shafts could be geared or otherwise connected in such a manner as to cause them to be reset in unison.

- 5 The "in" and "out" indicator is loosely mounted on the shaft 89 at the left hand end of the indicator 90 and differs from the ordinary "in" and "out" indicator in that it consists of a drum 110 having the words "in" and "out" arranged alternately about its periphery. This drum is driven by a gear 111 mounted on the shaft 89 and rigidly secured to the drum. This gear has wide teeth with concave surfaces and is 10 adapted to be actuated by a two-toothed gear 112. Mounted on the shaft 102 and having portions of its periphery, on the opposite sides thereof, convex and adapted to engage the concave edges on the teeth of the gear 111 to prevent overthrow of said gear. This two-toothed gear is preferably actuated through half a revolution each time the passenger indicators 93 are reset to zero, which is at the end of each trip. Consequently, the gear 111 will be advanced one point at the end of each trip, thus changing the reading of the "in" and "out" indicator. This is preferably accomplished by providing the shaft 102, to which the gear 112 is secured, with a gear 113 having on opposite sides thereof wide teeth 114 with concave edges. This gear is adapted to be engaged by the teeth of a mutilated gear 115 secured to the indicator shaft 89. The gear 115 has a single group of teeth on one side thereof and the space between the teeth at the ends of this group conforms to a segment of a circle described about the center of the shaft 89 and co-operates with the segmental teeth 114 of the gear 113 to check the movement of this gear and thus prevent the overthrow of the "in" and "out" indicator at the end of each operation thereof. The arrangement of the gears also prevents the turning of the indicator shaft while the indicator drum is being independently adjusted. A full revolution is imparted to the shaft 89 each time the passenger indicators are reset to zero. This causes the teeth of the mutilated gear 115 to engage the gear 113 and move the same through a half revolution, thus imparting a half revolution to the two-toothed gear 112 at the other end of the shaft 102 and advancing the "in" and "out" indicator 110 one space. Means are provided whereby the "in" and "out" indicator can be adjusted independently of the resetting shaft 89 in case this should be desirable. To this end the gear 113 is loosely mounted on the shaft 102 and is provided with a slotted hub 116 adapted to receive a tongue 117 carried by a sleeve 118 slidably mounted on the end of the shaft 102 and is provided with a knob or operating handle 119 which is arranged on the exterior of the casing or cabinet which encloses the machine. The sleeve 118 is connected to the shaft by means of a pin 120 which is secured to the shaft and projects through a slot 121 in the sleeve. A spring 122 tends to move the sleeve inward and thus hold the tongue normally in the slotted hub 116 to connect the gear 113 with the shaft 102. When it is desired to rotate the shaft independently of the gear the knob 119 is drawn outward to disconnect the sleeve from the gear and the desired movement is then imparted to the shaft. The gear 113 may be held against outward movement along with the sleeve 118 by means of a clip 123 secured to the side member of the main frame and adapted to enter a grooved sleeve 124 mounted on the shaft and secured to the inner side of the gear. Suitable mechanism is provided to prevent the overthrow of the indicator shaft when this shaft is rotated to return the indicators to zero. (See Fig. 45.) For this purpose the end of the shaft 89 on the outside of the end member 1 of the frame has secured thereto a collar 287 having formed therein a recess 288 and provided with a nose or projection 289. In the present arrangement of the mechanism this collar lies within a bell 272 and a stud 290 on which the bell is mounted supports two arms 291 and 292, each of which is rotatably mounted on said stud. On one side of the stud the arms 291 and 292 are substantially parallel and have confined between them a spring 293 which tends to separate those ends of the arms. The arm 291 has a nose 294 adapted to enter the recess 288 in the collar 287 and having connected thereto a spring 295 which tends to move the nose out of said recess. The arm 292 also has a nose 296 arranged in the path of the projection 289 on the collar. The rear edge of the recess 288 is preferably slightly concave so as to exert a gripping action on the end of the nose 294. This gripping action is very light, however, and the spring does not draw the nose out of the recess while the mechanism is idle. A slight rearward movement of the counter shaft will release the nose and permit the spring to withdraw it. The projection 289 on the collar is so arranged with reference to the recess 288 that the projection will engage the nose 296 just prior to the completion of the rotary movement of the shaft 89 and will rock the arm 292 and, through the action of the spring 293, the arm 291 about the axis of the shaft 290 and cause the nose 294 to enter the recess. At the completion of the rotation of the shaft and by the time the rear wall of the recess engages the nose 294 the projection 289 will have cleared the nose 296 and the nose 294 will be free to move under the action of the spring 295. The movement of the arms under the action of the

spring 295 is limited by a pin 297 adapted to be engaged by a nose 298 also carried by the arm 292.

Means are also provided for preventing the operation of the recording devices while the indicators are being reset to zero. (See Figs. 3 and 41.) To accomplish this a disk 299 is rigidly secured to the resetting shaft and an arm 300, pivotally mounted on the end of the setting shaft 41, has a nose 301 adapted to enter the recess in the disk 299 when the shaft 89 is in its normal position. The arm 300 has a tail piece 302 which projects beyond the shaft 41 and is adapted to be moved into and out of the path of a lug 303 carried by one side of the pawl 70. When the nose 301 is in the recess in the disk 299 the tail piece of the arm will be out of the path of the lug on the pawl and will not interfere with its movement. When the resetting movement of the shaft 89 has commenced the arm will be moved about its axis and the tail piece thereof moved into the path of the lug on the pawl, thus locking the pawl against movement and retaining the same in the path of the plate 66 of the operating mechanism and locking the operating mechanism against operating movement. As soon as the shaft 30 is returned to its normal position the nose of the arm will be moved into the recess by the action of a spring 304 and this movement of the arm will again carry the tail piece out of the path of the lug on the pawl 35 and the latter will be free to move, thereby releasing the operating mechanism.

The printed record carries the number of the car in which the machine is installed and to enable the machine to be used in different cars this number is preferably carried by a type plate 305, which is shown in Figs. 2, 19 and 47. This plate merely slips into a recess formed beneath the tie bar 5 and is held in position by means of a spring-pressed plunger 306 which automatically engages a recess in the upper side thereof.

A record may be taken from the printing counters in any suitable manner. Preferably it is printed on a web of paper and afterward removed from the machine. In the present machine we have employed a printing mechanism corresponding in its main features of construction and operation to that shown and described in the patent 55 to which we have above referred. This mechanism has been modified to such an extent as is necessary to adapt it to slightly different conditions existing in the present machine. Briefly, the printing mechanism 60 comprises a carriage consisting of side members 125 connected one to the other by rods 126, and provided at their lower edges with racks 127 which mesh with gears 128 secured to a printing shaft 129 journaled in the side members 1 and 2 of the frame and

adapted to be rotated to cause the operation of the printing mechanism. Mounted in the upper portion of the carriage is an inking roller 130 arranged to engage the type which are in printing position and ink the same during the first portion of the movement of the carriage. A platen 131 is mounted in the carriage in front of the inking roller and will press the paper against the type after the latter have been inked. 70 The shaft of the platen extends beyond the ends thereof and through vertical slots 132 formed in the side members of the carriage, thus causing the platen to travel with the carriage but permitting it to have vertical 75 movement relatively thereto. Each end of the platen shaft is provided with spring-pressed plungers 131^a which enter and travel in the grooves of a cam plate 133. The normal position of the carriage and 80 platen is that shown in Fig. 5. The first movement of the printing carriage will cause the platen to travel up the inclined grooves in the front portions of the cam plates, thus causing the platen to press the 85 paper against the type wheels. The further movement of the carriage causes the platen to travel along the upper horizontal grooves of the cam plates and thus causes the platen to pass over an electrotype plate 90 134 and other printing devices arranged in the same plane, such, for example, as the type on the conductor's key. The grooves in the cam plate are provided at their rear ends with shoulders over which the spring- 95 pressed plungers pass and which prevent the return of the platen along the upper groove and force the same to follow the lower groove upon the return movement of the carriage. This full movement is im- 100 partied to the printing carriage only when it is desired to print a total record, which record carries the headings which are printed by the electrotype plate. When a trip record is to be taken the carriage is moved 110 only far enough to cause the platen to print from the printing counters and is then re- 105 turned to its normal position. To prevent the platen traveling back over the type on the counter wheels intermediate inclined 115 grooves are formed in the cam plates and at their points of junction with the upper horizontal grooves are of a depth greater than the depth of the forward portions of said horizontal grooves so that when the spring- 120 pressed plungers have entered the upper ends of these intermediate inclined grooves they will be forced to move downward to their lower position upon the return move- 125 ment of the carriage. The lower horizontal grooves at their points of junction with the forward inclined grooves are of less depth than this forward groove and, consequently, the platen is prevented from moving rear- 130 wardly along the lower horizontal groove.

This mechanism, with the exception only of the specific arrangement of the grooves and the home position of the platen, is the same as that of the earlier machine.

- 5 The length of the side plates of the printing carriage, from front to rear, is rather short and in order to complete the full movement of the printing carriage supplemental driving gears 135 are mounted on 10 the side members of the frame in the rear of the gear 128 and are connected with these gears by means of idle gears 136. In course of the rearward movement of the carriage the rear ends of the plates will engage the 15 respective gears 135 before the front ends clear the respective gears 128 and, consequently, there will be no interruption of the movement of the carriage. The paper is preferably fed from a roll 137 supported 20 in the rear portion of the machine and is carried forward beneath the inking roller, over the platen and between the feeding rollers 138 arranged near the forward end of the machine.
- 25 The paper feeding rollers 138 are preferably actuated by the operation of the printing mechanism and are so controlled that a short length of paper will be fed forward upon each operation of the mechanism to 30 print a trip record and a longer length of paper will be fed forward each time the printing mechanism is operated to print a total record. To accomplish this result a cam plate 139, Fig. 4 is pivotally supported on the side member 1 of the main frame above the shaft 129 and is provided with a cam slot 140 which extends about an extension of the axis of the shaft 129, is arranged eccentrically thereto and has a 35 straight end portion. Rigidly secured to the shaft 129 is a disk 279 having secured thereto a pin 142 which extends into the cam slot 140. Rigidly secured to the plate 139 and preferably formed integral therewith is a segmental rack 143 meshing with a gear 144 loosely mounted on the shaft of one of the printing rollers 138 and having secured thereto an arm 145 carrying a spring-pressed pawl 146 which engages a 40 ratchet wheel 147 secured to the shaft of one of the paper feeding rollers 138. The shape of the cam slot 140 is such that when the shaft 129 is rotated through a distance sufficient to print the trip record only a short 45 movement will be imparted to the segmental rack 143 and when the shaft is rotated a distance sufficient to print a total record a longer movement is imparted to the segmental rack 143. The shaft 129 is positively moved in both directions and it will 50 be noted that the arrangement of the pawl and ratchet mechanism 146 and 147 is such that upon the first or outward movement of the segmental rack the pawl will travel 55 idly over the teeth of the ratchet but upon

the return movement of the rack the pawl will engage the teeth of the ratchet and operate the feeding roll. In this manner the paper feeding operation takes place at the close of the printing operation and after 70 the printing has been completed.

Rotary movement may be imparted to the shaft 129, to actuate the printing mechanism, in any suitable manner. In the present device that end of the shaft which 75 projects beyond the frame member 2 has secured thereto two pinions 148 and 149. (See Figs. 3 and 29 to 32.) These pinions are adapted to be actuated respectively by segmental racks 150 and 151. The rack 150 80 is adapted to mesh directly with the pinion 149 while the rack 151 is adapted to mesh with an idle gear 152 which has secured thereto and rotating therewith an idle gear 152^a which, in turn, meshes with the pinion 85 148. The two racks 150 and 151 are mounted on a stud 153 and may be actuated in any suitable manner as by means of a handle 154 arranged on the exterior of the casing which incloses the mechanism as a whole 90 and having a portion extending through an opening in that casing and connected with the stud 153. The racks 150 and 151 are normally out of mesh with the pinions 149 and 152, respectively. When the handle 154 is moved in one direction the rack 150 will actuate the pinion 149 and rotate the shaft 129 a distance sufficient to cause the printing mechanism to print a trip record and the return movement of the handle to its normal position will return the printing mechanism to its normal or home position. When the handle is moved in the other direction, the rack 151, which is considerably longer than the rack 150, will 100 95 engage the idle pinion 152 and through it and the idle gear 152^a actuate the pinion 148 and the shaft 129 a distance sufficient to cause the printing mechanism to print both from the printing counters and from 105 the electrotype plates, thus printing a total record. It will be noted that owing to the interposition of the idle gear 152 the direction of rotation of the shaft 129 is always 110 the same regardless of the direction in 115 which the handle 154 is moved. The segmental racks are rigidly secured one to the other and move in unison. Means are provided to make it necessary for the operator to move either rack through a complete 120 movement after the movement has once been started before the handle can be returned to its normal position. This means is here shown as a double full stroke mechanism of a well known character comprising 125 two segmental racks 155 and 156 arranged on opposite sides of a spring-held pawl 157.

A device is provided to lock the gears 148 and 149 against movement when the segmental racks 150 and 151 are in their nor- 130

mal or idle positions and thus maintain the gears in a position to be properly engaged by their respective pinions. Preferably means are also provided for advancing the 5 pinions a slight distance before they are locked in order that they may be in a position to more readily mesh with the respective racks when these latter are operated. To accomplish these two objects we have, in the 10 present machine, mounted on the outermost pinion 149 a pin 189. An arm 190 is rigidly secured to the segmental rack 151, projects beyond the edge thereof and has near the outer end of its inner face a transverse 15 groove 191 having its inner edge arranged eccentrically to the axis of the segmental racks. This arm 190 is so arranged with relation to the segmental racks that when either rack moves out of engagement with 20 its gear the pin 189 will enter the groove 191 in the arm and will remain in said groove so long as the segmental racks are in their idle positions. Consequently, the pinion 148 and the pinion 149, which is rigidly secured 25 thereto, are held against rotatory movement. The shape of the groove is such that the inner wall thereof will engage the pin as the latter enters the groove and the further movement of the arm as the rack completes 30 its movement will impart a slight movement to the gear and thus so position the teeth of the gear with relation to the teeth of the segmental rack that the latter will freely mesh with the former without danger of interference.

The movement of the printing handle in each direction may be positively limited in any suitable manner. (Fig. 3.) One very practical method of accomplishing this 40 consists in mounting a pin 283 in the end frame member 2 in the path of both edges of a segmental plate 248 which is loosely mounted on the stud 153 and rigidly connected with the printing handle. This plate is so arranged with reference to the movements of the handle that one edge will engage the pin 283 at the completion of the outward movement of the printing mechanism to print a trip record and the other edge of the plate 50 will engage the pin at the completion of the outward movement of the printing mechanism to print a total record.

The present machine is adapted to preserve two total records and to print these 55 records from the same set of printing counters from which the trip records are printed. This mechanism preferably comprises two sets of non-printing counters which are here shown as comprising ten-toothed gears and 60 may be referred to as accumulators inasmuch as they accumulate the count for several trips. As here shown each accumulator comprises a plurality of groups of gears which are indicated by the reference numerals 158 and 159, respectively, and are

mounted on shafts 160 and 161. (See Figs. 5, 7, 33 and 34.) These accumulator gears are provided with transfer mechanism comprising gears 260 and alining pawls 261 of a well known construction. The transfer 70 mechanisms for the two accumulators are carried by frames 262 and 263 secured to and forming parts of the tie bars 3 and 4, respectively. It will be noted in this connection that the two tie bars or support- 75 frames, and the transfer mechanism carried thereby are identical in construction and are interchangeable, thus enabling either to be used in either position. This is a valuable feature in the practical construction of the machine. Each accumulator shaft is a resetting shaft and is adapted to reset the accumulator gears in the same manner that the counters on the shaft 20 are reset and for this purpose each of these 80 shafts is provided at one end with a squared head, as shown in Fig. 4, to which a suitable key or socket wrench may be applied for rotating the shafts, thereby enabling each of the shafts to be reset separately from the other shaft, as well as from the printing counter shaft 20. The number of accumulator gears and their arrangements upon the respective shafts correspond with the number and arrangement of the 95 printing counter wheels on the shaft 20, excepting the machine total counters 15, and the accumulator gears are arranged in substantially the same vertical plane with the gears of the corresponding printing counters. The accumulator shafts are so arranged with relation to the printing counter shaft 20 and the actuator shaft 34 that the 100 actuators mounted on the shaft 34 will, upon each half revolution of that shaft, engage not only the gears of the printing counters which they may be set to actuate but also the corresponding accumulator gears, thereby adding to each accumulator the same 105 item or amount that is added to the printing counters. The printing counters are reset to zero at the end of each trip. The conductor's total counters, which, in the present instance, comprise the accumulator gears 158 on the shaft 160, are reset only at the 110 end of the conductor's run, or some similar period, and therefore will accumulate the total record of all items or amounts recorded on the printing counters during the several trips embraced in that run. The 115 inspector's total record, which, in the present machine, comprises the accumulator gears 159 on the shaft 161, is reset only at the end of the day or some other period embracing the runs made by several conductors, or any other similar period, and, therefore, will accumulate the totals of the 120 items and amounts recorded on the printing counters during the entire day. In this manner three separate and distinct records 125 130

are preserved and means are provided whereby these records may be printed.

The printing of the total records, as above stated, is accomplished by the printing counters on the shaft 20 and to this end means is provided for transferring the total counts from the respective accumulators to the printing counters in order that this count or record may be printed. Preferably, the transfer of the count from the accumulator counters to the printing counters is accomplished by moving the accumulator gears into mesh with the gears of the printing counters after the latter have been reset to zero, then resetting the accumulator gears to zero and thus advancing the printing counters a distance corresponding to the count which had been recorded by the accumulator gears. To permit of the ready movement of the accumulator gears into and out of mesh with the printing counter gears we have mounted the shafts 160 and 161 of the accumulators in arms 162 and 163, respectively, there being a pair of these arms for each shaft. Preferably, each pair of arms, that is, the two arms 162 and the two arms 163, are connected one to the other by means of tie bars 164 and 165 and the pair of arms and their tie bar constituting the supporting frame for the accumulator shafts, these shafts being journaled at their ends in the respective arms 162 and 163. If desired, an intermediate bearing lug may be provided between the two arms of each frame to form an additional support for the accumulator shaft. These supporting frames are mounted upon the frame of the machine and as here shown the adjacent arms of each pair are mounted on hollow studs or sleeves 166 mounted in the respective end members of the frame. In the present organization of the machine these hollow studs extend about the adjacent ends of the actuator shaft 34 so that the frames move about this shaft, but in order that the accumulator gears may move along lines adapted to cause them to mesh readily with the gears of the printing counters we have mounted the supporting frames to move on a common axis which is eccentric to the axis of the shaft 34, this being accomplished by making the sleeves or hollow studs 166 slightly eccentric. Springs 167 tend to move the accumulators outward toward their normal positions and to retain them in those positions. The outward movements of the accumulators are, in the present instance, limited by the tie bars 164 and 165 engaging collars 281 on the shaft 36. Preferably the tie bars are provided with projections 282 which can be machined to regulate the amount of outward movement which is to be permitted to the frames carrying the accumulators.

Any suitable means may be provided for

moving the accumulator shafts into and out of mesh with the printing counters. In the present form of the machine the squared ends of the accumulator shafts serve this purpose. When the end of one of these shafts is engaged by the key, or socket wrench, bodily movement can be readily imparted thereto, provided the several locking devices have been actuated to release the same.

A complete system of locks is provided to not only prevent the accidental displacement or movement of the various parts of the mechanism but to make it absolutely necessary that the operations be performed in the proper sequence, thereby insuring that each record is made and that it is a correct record. The accumulators cannot be reset to zero except when they are in mesh with the gears of the printing counters. When in their normal positions their shafts are locked against rotation by means of lugs 168, Fig. 4, secured to the end member 1 of the frame near the respective shafts and adapted to enter notches in disks 169 rigidly secured to the respective shafts and so arranged with reference to the lugs 168 that when the accumulator shaft is moved outward into its normal position the lug will enter the recess, thus locking the shaft against rotation. The disks 169 rotate with the resetting shafts and the notches are so arranged therein that they will be in alignment with their respective lugs 168 only when the accumulator shafts have been reset to zero. Consequently, the accumulator shafts cannot be returned to their normal positions until they have been reset to zero. The length of the lugs 168 is preferably such that the accumulator gears will be retained in mesh with the gears of the printing counters until the accumulator gears have been reset to zero.

It is essential that the printing counters should be reset to zero before either accumulator is moved into mesh therewith. Otherwise, the record which is transferred from the accumulator to the printing counters would be a garbled record because it would be merely added to the record already contained by the printing counters. We have, therefore, provided means to prevent either accumulator from being moved into mesh with the printing counters until these latter have been reset to zero. This result may be secured in any suitable manner but that here shown is simple and highly efficient. This mechanism is shown in Fig. 33 of the drawings and comprises a gear 170 loosely mounted on the printing counter shaft 20, preferably near one end thereof, and held against accidental displacement by means of a pinion 171 and a spring-pressed pawl 172 engaging the pinion. This gear, 170, is adapted to be returned to its initial position in the

same manner that the printing counters are reset, that is, by the key in the resetting shaft engaging a pin carried by the gear. The gear 170 has one tooth cut away to provide a wide space 173 between two of its teeth, and the teeth on each side of this wide space are of extra width, as indicated at 174 and 175. In the present instance the width of each of these teeth is equal to the width of two of the ordinary teeth plus the space between these two teeth. Mounted on the accumulator shaft 160 is a mutilated gear 176 having a wide tooth 177 also provided with a plurality of detent teeth 180 adapted to receive between them a detent, such as the spring 181, to hold the gear against accidental displacement but permitting it to move when force is applied thereto. A gear 182 is mounted on the accumulator shaft 161 and has two teeth 183 and 184 which are of ordinary width and are spaced apart a suitable distance. This gear is also provided with detent teeth 186 cooperating with a detent 187 similar to the detent 181. The gears 176 and 182 on the accumulator shafts are arranged in the same vertical plane with the gear 170 on the printing counter shaft. In Fig. 33 the several gears are shown in the positions which they occupy when each resetting shaft has been reset and all the counters on all the shafts are at zero. Mounted on the actuator shaft 34 in the plane of the gears 170, 176 and 182 is a two-toothed actuator 188 similar to the other actuators on this shaft. Upon the first operation of the shaft 34 to record the first fare received after the several shafts have been reset to zero this actuator will engage the teeth 177, 175 and 184 of the respective gears and advance each gear one space. Inasmuch as that tooth of each gear immediately following the teeth above mentioned has been cut away it will be apparent that the further operation of the actuating shaft 188 will not affect the positions of the gears 170, 176 and 182. As a result of this movement of the gears through a single space the teeth 174 and 177 of the gears 170 and 176, respectively, are moved into substantial alinement and in this position any downward movement of the accumulator shaft 160 would cause the teeth 177 to engage the tooth 174, which engagement would effectually prevent any further movement of the accumulator shaft, and, consequently, the accumulator gears would be effectually locked out of mesh with the gears of the printing counters. Likewise, the tooth 183 of the gear 182 will be moved into alinement with the tooth 175 of the gear 170 and, consequently, the accumulator shaft 161 will be locked in a position in which its gears cannot mesh with the printing counter gears. When the printing counter shaft 20 is reset to zero along with the printing counters the

space 173 will be moved into alinement with the tooth 177 of the gear 176 and this gear and its shaft 160 can then be moved toward the printing counter shaft to carry the gears of the accumulator shaft 160 into mesh with the gears of the printing counters. Mounted on the shaft 160 and secured to the gear 176 is a second mutilated gear having two teeth 178 and 179 arranged on opposite sides of the wide tooth 177 of the gear 176. A gear 192 is mounted on the shaft 20 and secured to the gear 170. Consequently, when the accumulator gears are moved into mesh with the gears of the printing counters the tooth 178 will mesh with the gear 192 and the rotation of the shaft 160 to reset the accumulator gears to zero will move the gear 170 through one space, thus again moving the tooth 175 into a position to engage the tooth 183 of the gear 182, which gear, it will be remembered, has already been advanced one space by the action of the two-toothed gear on the shaft 34. It is, therefore, impossible to move the accumulator shaft 161, which records the inspector's total, to cause its gears to mesh with the gears of the printing counters until the printing counters have been again reset to zero after receiving the conductor's total.

A one-toothed gear 193 is mounted on the inspector's accumulator shaft 161 and secured to the gear 182 in such a position that its tooth will mesh with the gear 192 on the shaft 20 and assist in advancing the gears 192 and 170 one space when the inspector's accumulator gears are reset to zero, thus moving the tooth 174 of the gear 170 into such a position as to prevent the downward movement of the conductor's accumulator shaft 160 until the printing counters have been again reset to zero. In this connection it may be noted that both accumulator shafts reset in a direction opposite the usual direction, that is, to say, they reset from 9 to 0. As a result the gear 170 can be moved through but one space when either accumulator shaft is rotated to reset its counters to zero. The movement of the gears 176 and 182 in each direction is limited by means of stops, such as pins 380, driven into the tie bars 164 and 165 of the respective accumulator frames and arranged in position to be engaged by the teeth of the gears 179 and the detent teeth 180 of the gear 176 and the tooth 184 and detent tooth 186 of the gear 182, thus positively checking the movement of these parts.

Means are also provided for preventing the resetting of the printing counters until a record has been printed therefrom. This mechanism is shown in Figs. 4 and 42 and comprises a pawl 194 arranged normally in the path of a tapered nose or projection 195 secured to a collar 196 which, in turn, is rigidly secured to the printing counter re-

setting shaft 20. Thus, in its normal position this pawl 194 will lock the resetting shaft against rotation and against resetting. This pawl is moved out of the path of the 5 nose 195 by the operation of the printing mechanism to release the resetting shaft and permit the counters thereon to be returned to zero. To this end the pawl 194, which is pivotally mounted on a stud 197, has secured thereto an arm 198 on which is pivotally mounted a pawl 199. An arm 200 secured to the pawl 199 is acted upon by a spring 201 to hold the arm normally against a pin 202 on the arm 198. A disk 203 is 10 rigidly secured to the printing shaft 129 and has mounted on one side thereof a projection, such as a pin 204, which is so arranged with reference to the pawl 199 that when the first printing movement is imparted to 15 the shaft 129 the projection will engage the pawl 199, move the same about its pivotal center against the tension of the spring 201 and pass the same. Upon the return movement of the shaft the pin will engage the 20 opposite edge of the pawl 199 and inasmuch as the pawl is held against movement beyond a fixed point by the pin 202 both the pawl 199 and the arm 198 will be caused to move with the disk 203 until the pin clears 25 the pawl 199, thus moving the locking pawl 194 about its axis and carrying it out of the path of the nose 195 on the collar which is secured to the resetting shaft 20, thereby releasing this shaft and permitting it to be 30 rotated in a direction to reset the counters. To retain the locking pawl 194 in its inoperative position until the counters can be reset a second arm 205 is connected with the locking pawl 194 and the arm 198 and extends 35 rearwardly from the pawl 194. A locking dog 206 having a nose 207 is held normally in engagement with the end of the arm 205 by means of a spring 208 which is connected with a projection 209 secured to the dog 206. When the locking pawl 194 is 40 moved into its inoperative position the end of the arm 205 will move past the nose on the dog 206 and the spring 208 will move the dog toward the arm and cause the nose 45 thereof to extend over the end of the arm, thus holding the arm 205 against upward movement and securing the locking pawl 194 in an inoperative position. The locking pawl 194 is retained in this inoperative position 50 until rotatory movement has been imparted to the resetting shaft 20 when it is released and caused to again move into an operative position. To this end a disk 210 is secured to the resetting shaft 20 and has in the edge 55 thereof a recess 211 adapted to receive a nose 212 secured to the adjacent edge of an arm 213 which is mounted on the stud 197 and has secured thereto two fingers 214 and 215. The finger 214 is acted upon by a spring 216 60 to move the arm 213 toward the disk 210. The finger 215 is arranged to engage a toe 217 on the projection 209 which is secured to the dog 206. Thus, as soon as the resetting movement of the shaft 20 begins the nose 212 of the arm 213 will be forced out 65 of the recess 211 in the disk 210 and the arm and the fingers connected therewith moved against the tension of the spring 216. The movement of the finger 215 causes it to engage the toe 217 on the projection 209 and 70 rock this projection and the dog 206 about their pivotal support to release the arm 205 which is then acted upon by a spring 218 to cause the locking pawl 194 to move toward the resetting shaft 20. The release of the 75 locking pawl 194 takes place immediately after the nose 195 of the collar 196 passes the end of the locking pawl and, consequently, the locking pawl is in a position to again engage the nose when it has completed 80 a single revolution, thus again locking it against movement and, further, preventing its overthrow.

It is desirable that the printing mechanism should be in its home or normal position 85 before the resetting of the printing counters takes place. To make this necessary the disk 203, which is mounted on the printing shaft 129, has formed therein a notch 280 which is so arranged with relation to the printing mechanism that when the latter is in its normal position the notch 280 will be in a position to receive the end 90 of the arm 213, which is actuated by the resetting of the printing counter shaft 20. 100 If the printing mechanism is not in its normal position the end of the arm 213 will engage the periphery of the disk 203 and the nose 212 on the arm 213 will be held in the notch 211 in the disk 210 on the printing counter shaft and this shaft held against 105 rotation. It will be apparent from this construction that not only must the printing mechanism be in its home position before the resetting of the printing counters can 110 begin but after the resetting has been started the end of the arm 213 will be held in the recess in the disk 203 and the printing mechanism locked against operation until the resetting shaft has completed its rotation and 115 the notch in the disk 210 is once more brought opposite the nose 212 on the arm 213.

Means are also provided to prevent the printing mechanism being operated more 120 than once and thus more than one impression taken from the same record on the printing counters. This device is here shown as operated in connection with the locking mechanism just described and, to 125 this end, the arm 198 is provided with a portion 219 which extends beyond the pawl 199. Pivotally mounted on the frame of the machine is an arm 220, one end of which overlaps the portion 219 of the lever 198. 130

The other end of the lever 220 is acted upon by a spring 221 which tends to move the lever toward the portion 219 of the arm 198. Pivotally mounted on the same axis with the lever 220 is a finger or locking dog 222 which is caused to move in one direction with the lever 220 by means of a spring 223 confined between the adjacent portions of the dog and the lever and is caused to move in the other direction with the lever by means of a lip 224 carried by an extension 225 of the arm 222 and extending beneath the adjacent portion of the lever 220. A second disk, 279, is rigidly secured to the shaft 129 adjacent to the disk 203 and has formed therein a notch 226 which, when the printing mechanism is in its idle position, will be in alinement with the dog 222. When the arm 198 is actuated by the return of the printing mechanism to move the locking pawl 194 into its inoperative position the lever 220 will be moved about its pivotal center and, through the spring 223, the dog 222 will be caused to bear upon the periphery of the disk 203. As soon as the printing mechanism has completed its return stroke, which is made necessary by the full stroke mechanism above described, the dog 222 will be forced into the recess 226 and the printing mechanism locked against further operation. The printing mechanism will remain locked until the printing counters have been reset to zero and the locking pawl 194 released, as above described. The movement of the locking pawl into its operative position causes the portion 219 of the arm 198 to move toward the printing shaft 129, thus permitting the lever 220 to move about its pivotal center under the influence of the spring 221. This movement of the lever 220 is transmitted to the dog 222 through the lip 224 and extension 225 and the dog is thus moved out of the recess 226 and the printing mechanism released. A device is also provided to lock the two accumulator shafts against movement toward the printing counters during the printing operation. To accomplish this the disk 279 has formed in the edge thereof a recess 227 and a lever 228 is pivotally mounted between its ends on the stud 197 and has a nose 229 arranged to enter the recess 227. The lever 228 is provided with a shoulder having recesses 230 to receive a spring-pressed detent pawl 231 which tends to hold the lever in adjusted positions until positive force is applied thereto. This lever also has an arm 232 arranged to be moved into and out of the path of the squared end of the accumulator shaft 160. Another arm 233 is mounted on the stud 197 and rigidly connected with the lever 228 so that the arms 232 and 233 will move in unison. This arm 233 is adapted to be moved into and out of the path of the accumulator shaft 161 when

the arm 232 is moved into or out of the path of the shaft 160. This second arm 233 extends across the shaft 20 and is provided with a slot 234 through which the shaft extends and which permits the arm to move freely with relation to the shaft. It will be apparent from the arrangement of the several parts that the first movement imparted to the disk 279 by the printing handle will force the nose 229 of the lever 228 out of the recess in the disk 279 and thus move the lever about its pivotal center a distance sufficient to move the arms 232 and 233 into the paths of the respective accumulator shafts and thus lock these shafts against movement toward the printing counter shaft. These locking arms remain in their locking positions until a record has been printed and the printing counter shaft reset to zero, the rotation of this shaft serving to move the locking arms into their inoperative positions and release the accumulator shafts. This last result is secured by providing the arm 232 with a nose 235 which is so arranged that the movement of the arm 232 into its locking position will move the nose 235 into a position immediately in the rear of a projection 236 mounted on a collar secured to the resetting shaft 20 for the printing counters. Both the nose 235 and the projection 236 have inclined edges and as the shaft 20 approaches the end of its resetting movement the projection will engage the nose on the arm 232 and move the arm and, consequently, the lever 228 about their pivotal support, thus carrying both the arms 232 and 233 out of the paths of their respective accumulator shafts and moving the nose 229 of the lever again into the recess 227 of the disk 203. It will also be apparent that so long as either accumulator is in operative relation with the printing counters the end of the shaft of that accumulator will lie in the path of the arm 232 or 233, as the case may be, thus retaining the arm 228 in locking relation to the printing mechanism.

It is also desirable that the recording mechanism should be locked against operation during the printing movement. For this purpose we have provided the shaft 61 with a segmental plate 237 and have provided the lever 228 with an arm 238 arranged to be moved into and out of the path of the segmental locking plate carried by the shaft 61 simultaneously with the movement of the lever to lock and unlock the accumulator shafts. The segmental plate 237 remains in contact with the arm 238 while the actuator is being operated, thus locking the printing mechanism against movement while a fare is being recorded. In connection with this same mechanism we have also provided a device for locking the printing mechanism against operation at all times except when the setting shaft is in such a posi-

tion that the actuators will be in their neutral positions, as above described, and for retaining the actuators in their neutral positions during the operation of the printing mechanism. This device comprises a disk 239 secured to the setting shaft 41 and having therein a recess 240. Pivotally mounted on the shaft 61 is an arm 241 having a tapered nose arranged to bear normally upon the periphery of the disk 239. This arm has a tail portion, as shown at 242, which is adapted to be moved into and out of the path of a lug or block 243 secured to one side of the arm 238 of the lever 228. A spring 244 tends to move the arm 241 inward and to hold its nose against the periphery of the disk. So long as the nose of the arm 241 rests upon the periphery of the disk the tail 242 of the arm will extend into the path of the projection on the arm 238 and the lever 228 will be held against movement, thus holding the nose 229 of the lever in the recess 227 of the disk 203 and locking the printing shaft against rotation. The movement of the setting shaft into its neutral position brings the recess 240 of the disk 239 into alignment with the nose of the arm 241 and the spring 244 causes the nose to enter the recess, thus moving the arm about the axis of the shaft 61 and carrying the tail 242 of the arm out of the path of the projection 243 and permitting the lever 228 to move about its axis. During the operation of the printing mechanism the nose of the lever 228 will ride on the periphery of the disk 203 and the nose of the arm 241 will be retained in the recess of the disk 239, thus locking the setting shaft and actuators against movement.

Not only is the printing mechanism locked against operation except when the setting shaft is in its neutral position, but the accumulator shafts are locked in their outermost positions except when the setting shaft is in its neutral position. This latter function is accomplished by securing to each of the accumulator shafts 160 and 161 a strap, 264 and 265, Figs. 5 and 13, each having at its upper end a transverse lip, 266 and 267, extending across disks 268 and 269, one disk being mounted on the setting shaft 41 and the other on the indicator shaft 89. The disk 269 is loosely mounted on the shaft 89 and has connected therewith a gear 285 which meshes with a gear 286 mounted on the setting shaft 41 and secured thereto in such a manner as to rotate in unison with said shaft and with the disk 268 which is also secured to the shaft 41. By this arrangement the disks will be caused to rotate in unison in opposite directions. Each disk has formed therein a recess, 270 and 271, so arranged that when the setting shaft is in neutral position the recesses will be in alignment with the lips of the respective straps and the ac-

cumulator shafts will be permitted to move toward the printing counter shaft as soon as the other locking mechanisms have been released. At all times save when the setting shaft is in its neutral position any movement of either accumulator shaft toward the printing counter shaft will cause the lip of the respective strap to engage the periphery of its disk and the further movement of that accumulator shaft will be prevented. This mechanism also prevents the movement of the setting shaft while either accumulator is in operative relation with the printing counters.

As has been above stated the printing handle 154 is moved in one direction to cause the printing mechanism to print from the printing counters only and in the opposite direction to cause the printing mechanism to print both from the printing counters and from the electrotype plate, etc., the first record constituting a trip record and the second record constituting a total record. The direction of movement of the handle is positively controlled so that it cannot be accidentally or otherwise moved in the wrong direction when it is desired to print a record of either kind. The mechanism by means of which this control is accomplished comprises two disks 245 and 246 each having in one side a curved recess. (See Figs. 6, 29, 30, 35 to 39.) These disks are mounted on the shaft 22 which is arranged in alignment with the printing counter shaft and are arranged with their recessed portions in different positions relative to the horizontal. The disk 245 is arranged in the same plane with the segmental rack 150, which rack is provided with a segmental extension 247, and the disk 246 is arranged in the same plane with the segmental plate 248 rigidly secured to the stud 153, which stud also carries the segmental racks 150 and 152 and the printing handle 154. The two disks 245 and 246 are rigidly secured to the shaft 22 and are rigidly connected one to the other and to a disk 249 also mounted on the shaft 22. These three disks are held normally against movement by means of a spring-pressed pawl 250 which engages a star wheel 251 rigidly secured to the shaft 22. When the counters on all the shafts have been reset to zero the two disks 245 and 246 will occupy the positions shown in Figs. 29 and 30, respectively, and it will be noted that the disk 245 will extend into the path of the segmental extension on the rack 150 and that this segment and, consequently, the printing handle are locked against movement in one direction. The disk 246 will have its cut away portion or recess in such relation to the plate 248 that this plate can pass through the recess, thus permitting the handle to move in this direction. However, the counters being all set at zero a zero record will be 130

printed. The first operation of the register to record a fare will advance the disks 245 and 246 a distance sufficient to move the recess in the disk 245 into such a position 5 relatively to the rack 150 that this extension can pass through the recess, thus permitting the operating handle to be moved to print a trip record any time after the first fare has been recorded. This same movement of the 10 disks, however, moves the recess of the disk 246 into such a position relatively to the plate 248 that this plate is locked against movement in one direction and the printing handle cannot be actuated in a direction to 15 print a total record. This movement of the disks is secured by means of a two toothed actuator 252 on the shaft 34 which coöperates with the disk 249, which disk is connected with the disks 245 and 246 and is provided 20 with a single operating tooth which is indicated at 253 and is in the form of a shoulder. That portion of the disk extending forwardly from the shoulder conforms to an arc of a circle described about the center of the shaft 22. Immediately in the rear of the tooth or shoulder 253 is a cut away portion or curved recess 254. The teeth on the two-toothed actuator 252 are broad segment-shaped teeth and their forward edges 25 are arranged to engage the tooth or shoulder 253 of the disk 249. After the disk 249 has been advanced one space by the first operation of the actuator shaft and its two-toothed actuator, the curved recess 254 will be 30 positioned with relation to the actuator that the teeth thereof will pass through the recess without engaging the disk or altering its position. Consequently, the positions of the disks 245 and 246 are affected only by 35 the registration of the first fare. It will be noted that the recess 254 serves also to prevent the overthrow of the disks 245 and 246, this being due to the fact that the edge of the recess 254 will engage the segmental edge 40 of the tooth of the actuator before the latter has cleared the recess and will thus check the movement of the disk 249 and the parts connected thereto.

Not only can any number of fares be recorded after the recordation of the first fare, without affecting the positions of the disks 245 and 246, but the printing counters can be reset to zero and a series of trip records printed without affecting the positions 50 of these disks. The locking plate 248 of the printing handle is released to permit a total record to be printed by the act of resetting the conductor's accumulator 160 to zero.

60 Mounted on the shaft 22 and rigidly secured to the disks, 245, 246 and 249 is a gear 255 having one tooth cut away, as indicated at 256. A full gear 257 is mounted on the accumulator shaft 160 and is adapted 65 to rotate with that shaft when the latter

is actuated to reset the gears thereon to zero. When it is desired to print a conductor's total record the accumulator shaft 160 is moved downward to cause the gears thereon to mesh with the gears of the printing counters. This action causes the gear 257 to mesh with the gear 255 on the shaft 22. This latter gear is so arranged that that portion thereof from which the tooth has been removed will be adjacent to the accumulator shaft 160 until the first fare has been recorded. The recordation of this first fare actuates this gear, along with the disks, to advance the gear one space. Consequently, when the accumulator shaft is 70 moved downward the gear 257 will mesh with those teeth immediately following the space 256 in the gear 255. The rotation of the gear 257 when the accumulator is reset to zero will cause the gear 255 and the parts 75 connected therewith to advance nine spaces, thus completing the revolution of the gear and the disks and causing the disks 245 and 246 to assume the position first described, in which the printing handle was locked 80 against movement to print a trip record but was free to print a total record. The locking mechanism remains in this position until the machine has been operated to record another fare. Therefore, if desired, an 85 inspector's total record may also be printed but this cannot be done until after the conductor's accumulator has been reset to zero. To make it necessary to take the conductor's record before an inspector's record can be 90 taken a disk 258 is mounted on the shaft 22 and has a curved recess in that edge thereof adjacent to the inspector's accumulator shaft. The disk 258 is arranged in the same plane with a disk 259 mounted on 95 the inspector's accumulator shaft 161. The disk 258 is connected with the disks 245 and 246 and has its recess so arranged with relation to the disk 259 that it will be moved into alinement with that disk only when 100 the gears on the conductor's accumulator shaft have been reset to zero. At all other times the periphery of the disk will bear 105 such relation to the disk 259 that the shaft 161 is held against movement toward the 110 printing counter shaft 20.

The machine is also provided with a bell adapted to ring each time a fare is recorded. This bell is shown at 272 as mounted on one of the end frame members of the machine. 115 A hammer 273 is pivotally supported adjacent to the actuator shaft 34 and has a finger 274 extending toward that shaft and adapted to be engaged by either of two inclined projections 275 arranged on opposite 120 sides of the shaft 34. The hammer also has an arm 276 which is connected by a spring 277 to a fixed part of the frame and tends to move the hammer toward the bell. Each time the actuator shaft 34 is moved through 125 130

a half revolution the arm 274 will ride over one of the inclined projections 275 and move the hammer away from the pawl against the tension of the spring 277. As the straight 5 end of the cam projection passes the end of the arm 274 the spring will move the hammer forcibly toward the bell. Preferably, the arm 274 will bear normally upon a collar 278, which carries the tapered projections 275, and hold the hammer just out of 10 engagement with the bell. The resiliency of the hammer arm is such that when it is moved forward under the action of the spring the head of the hammer will strike 15 the bell but will immediately rebound out of contact with the bell, thus avoiding any interference with the vibration of the bell.

The operation of the mechanism will be 20 readily understood from the foregoing description and it will be apparent that the machine which we have constructed is simple in its construction and operation; that it employs a relatively small number of parts and that these parts and the construction of the 25 machine as a whole are of such a character as to produce a very strong, durable machine and one which cannot be easily broken or disarranged even by the most severe use or abuse. Further than this the machine has 30 a certain amount of flexibility, as for example, in the operating mechanism, the throw of which is such that it will automatically accommodate itself to various conditions in different installations or to varying 35 conditions in the same installation. This strength and durability is attained without increase in cost but rather with a decreased cost. The metal and the labor required to construct the machine have been materially 40 reduced. It will further be apparent that the machine is provided with a system of strong, durable locks which are automatically operated or released to permit each 45 operation of the machine to take place in the prescribed sequence and to effectually prevent any operation of any part of the machine at such a time as would destroy or in any way interfere with the records which it is desired to preserve.

50 While we have shown the mechanism embodied in a street car fare register it will be obvious that it is applicable to recording and computing machines of various kinds and it will be understood that the present 55 embodiment is chosen for the purpose of illustration only and that we do not desire to be limited to the details of construction shown and described, for obvious modifications will occur to a person skilled in the 60 art.

Having thus fully described our invention, what we claim as new and desire to secure by Letters Patent, is:—

1. In a machine of the character described, 65 the combination, with a counting device, of

a plurality of accumulating devices, means for actuating said devices by one operation to cause each to record the same item, and means to separately transfer the records from the respective accumulating devices to 70 said counting device.

2. In a machine of the character described, the combination, with a counting device comprising printing counters, of a plurality of accumulators each comprising non-printing 75 counters, means for actuating said counting device and said accumulators by one operation to cause each to record the same item, and means to cause records to be taken from said printing device and said accumulators 80 in a predetermined order.

3. In a machine of the character described, the combination, with a counting device comprising printing counters, of a plurality of accumulators each comprising non-printing 85 counters, means for actuating said counting device and said accumulators by one operation to cause each to record the same item, and independently operable means to transfer the records from the accumulators to 90 said counting device.

4. In a machine of the character described, the combination, with a counting device, of a plurality of accumulators, means for actuating said counting device and said accumulators to cause each to record the same item, and independently operable means to transfer the records from said accumulators to 95 said counting device.

5. In a machine of the character described, 100 the combination, with a counting device, of a plurality of accumulators normally disconnected from said counting device, means for actuating said counting device and said accumulators, while disconnected, to cause 105 each to record the same item, and means for separately connecting said accumulators with said counting device and for separately transferring the records from said accumulators to said counting device. 110

6. In a machine of the character described, the combination, with a counting device comprising a series of gears, of a plurality of accumulators each comprising a series of gears corresponding to the series of gears 115 of said counting device, the gears of each of said accumulators being capable of separate movement into and out of mesh with the gears of said counting device, means to actuate the corresponding gears of said 120 counting device and of said plurality of accumulators, while out of mesh, to cause each to record the same item, and means to actuate the gears of each accumulator while in mesh with the gears of said counting device 125 to cause the record of that accumulator to be transferred to said counting device.

7. In a machine of the character described, the combination, with a group of printing counters each comprising a gear, of two non- 130

printing accumulators each comprising a group of gears, an actuating device arranged to engage and actuate upon each operation thereof a gear of said group of 5 printing counters and of each of said accumulators, independently movable supports for said accumulators to enable the same to be moved separately into mesh with said printing counters, and means for transferring 10 a record from said accumulators to said printing counters.

8. In a machine of the character described, the combination, with a counting device, of a plurality of accumulators separately 15 mounted on a common axis for independent movement into and out of operative relation with said counting device, and an actuator adapted to actuate said counting device and said accumulators to cause each to register a 20 unit.

9. In a device of the character described, a counting device comprising a shaft, a series of printing counters mounted thereon, and means for resetting said printing 25 counters to zero, of two accumulators comprising shafts extending substantially parallel with the first mentioned shaft, and a series of counters mounted on each of said last-mentioned shafts, a supporting frame 30 for each of said last-mentioned shafts arranged to permit said accumulators to be moved into and out of operative relation with said printing counters, an actuator shaft extending parallel with the other 35 shafts, an actuator mounted on said actuator shaft and adapted to engage and operate upon each operation thereof a counter on each of said shafts to cause said counting device and each of said accumulators 40 to record the same item, and means for operating said actuator.

10. In a machine of the character described, the combination, with a counting device comprising a shaft, and a plurality 45 of printing counters mounted thereon, each of said counters comprising a gear, an actuator shaft arranged substantially parallel with said counter shaft, and an actuator mounted thereon and adapted to engage the 50 gear of one of said counters, of two supporting frames pivotally mounted on said actuator shaft and extending on the opposite sides thereof, a shaft carried by each of said supporting frames, a series of 55 counters mounted on each of said shafts and each comprising a gear, said shafts being normally supported in such a position that said actuator will, upon each operation thereof, operatively engage a counter on 60 each of said last-mentioned shafts as well as on the first-mentioned counter shafts.

11. In a machine of the character described, the combination, with a counter shaft, a series of counters mounted thereon, 65 an actuator shaft, two supporting frames

pivots mounted on said actuator shaft on an axis eccentric to the axis of said actuator shaft, an accumulator carried by each of said supporting frames and comprising a series of counters corresponding to the 70 counters on said counter shaft, and an actuator mounted on said actuator shaft and adapted to operatively engage on each operation thereof one of the counters on said counter shaft and also one of the counters 75 of each of said accumulators.

12. In a machine of the character described, the combination, with a counter shaft, a series of counters mounted thereon and each comprising a gear, an actuator 80 shaft substantially parallel with said counter shaft, a supporting frame mounted on said actuator shaft, an accumulator carried by said supporting frame and comprising gears adapted to mesh with the gears of 85 said counters, an actuator gear mounted on said actuator shaft and adapted to engage on each operation thereof corresponding gears of said accumulator and said counters, said supporting frame for said accumulator 90 being movable to cause said accumulator gears to move into and out of mesh with said counter gears.

13. In a machine of the character described, the combination, with a counter 95 shaft, a series of counters mounted thereon and each comprising a gear, an actuator shaft substantially parallel with said counter shaft, a supporting frame mounted on said actuator shaft, an accumulator carried by said supporting frame and comprising gears adapted to mesh with the gears of 100 said counters, an actuator gear mounted on said actuator shaft and adapted to engage on each operation thereof corresponding 105 gears of said accumulator and said counters, said supporting frame for said accumulator being movable to cause said accumulator gears to move into and out of mesh with said counter gears, and having its axis eccentric to the axis of said actuator shaft.

14. In a machine of the character described, the combination, with a counter shaft, a series of counters mounted thereon and each comprising a gear, an actuator 115 shaft substantially parallel with the counter shaft, an actuator mounted on said shaft, a supporting frame mounted in said machine and having bearing portions extending about the axis of said actuator shaft, an 120 accumulator carried by said supporting frame and comprising gears adapted to mesh with the gears of said counters, said supporting frame being movable to cause the accumulator gears to move into and out of 125 mesh with the counter gears and having its axis eccentric to the axis of said actuator shaft.

15. In a machine of the character described, the combination, with a counter 130

- shaft, a series of counters mounted thereon, a plurality of accumulators each comprising a series of counters, supported adjacent to said counter shaft and adapted to be moved 5 into and out of operative relation with the counters thereon, an actuator arranged to actuate upon each operation thereof one counter on said counter shaft and on each of said accumulators, transfer mechanism 10 for each of said accumulators, and fixed supporting frames for said transfer mechanisms, said fixed supporting frames being interchangeable.
16. In a machine of the character described, the combination, with a counting device and an actuating device therefor, of means for imparting rotatory movement to said actuating device comprising two mutilated gears connected with said actuating device and with one another, and a toothed device having movement in two directions and adapted to engage one of said mutilated gears when moved in one direction and to engage the other of said mutilated gears 25 when moved in the other direction.
17. In a machine of the character described, the combination, with a counting device and an actuating device therefor, of mechanism for imparting movement to said actuating device comprising two mutilated gears connected with said actuating device and one with the other, each of said mutilated gears comprising two groups of teeth arranged on opposite sides thereof 30 and said gears being so arranged with relation one to the other that the groups of teeth on each of said mutilated gears will lie adjacent to the corresponding spaces between the groups of teeth on the other of said 35 gears, and a toothed operating member having movement in two directions and adapted to engage the teeth of one of said mutilated gears when moved in one direction and the teeth of the other of said mutilated gears 40 when moved in the other direction, whereby both of said gears and said actuating device, with which they are connected, will be rotated in the same direction upon each operation of said toothed operating member.
18. In a machine of the character described, the combination, with a counting device and an actuating device therefor, of mechanism for imparting movement to said actuating device comprising two mutilated 45 gears connected with said actuating device and one with the other, each of said mutilated gears comprising two groups of teeth arranged on opposite sides thereof, said gears being arranged in the same plane and so positioned relatively one to the other that when rotated the groups of teeth of each of said gears will lie adjacent to the corresponding spaces between the groups of teeth of the other gear, and a toothed operating 50 member arranged in the same plane with
- said mutilated gears and movable in two directions, whereby it will be caused to engage the teeth of one of said mutilated gears when moved in one direction and the teeth of the other of said mutilated gears when moved in the opposite direction.
19. In a machine of the character described, the combination, with a counting device and an actuating device therefor, of mechanism for imparting movement to said actuating device comprising two mutilated gears connected with said actuating device and one with the other, each of said mutilated gears comprising two groups of teeth arranged on opposite sides thereof, said 55 gears being arranged in the same plane and so positioned relatively one to the other that when rotated the groups of teeth of each of said gears will lie adjacent to the corresponding spaces between the groups of teeth of the other gear, a segmental rack pivotally supported in substantially the same plane with said mutilated gears and so arranged that when oscillatory movement is imparted thereto it will alternately engage the teeth 60 of the respective mutilated gears.
20. In a machine of the character described, the combination, with a counting device and an actuating device therefor, of mechanism for imparting movement to said actuating device comprising two mutilated gears connected with said actuating device and one with the other, each of said mutilated gears comprising two groups of teeth arranged on opposite sides thereof and said 65 gears being so arranged with relation one to the other that the groups of teeth on each of said mutilated gears will lie adjacent to the corresponding spaces between the groups of teeth on the other of said gears, a toothed operating member having movement in two directions and adapted to engage the teeth of one of said mutilated gears when moved in one direction and the teeth of the other of said mutilated gears when moved in the 70 other direction, whereby both of said gears and said actuating device, with which they are connected, will be rotated in the same direction upon each operation of said toothed operating member, a locking plate 75 secured to and rotatable in unison with one of said mutilated gears, and a part movable with said toothed operating member to engage said locking plate and check the movement of said mutilated gears, thereby preventing the overthrow of said actuating device.
21. In a machine of the character described, the combination, with a counting device and an actuating device therefor, of mechanism for imparting movement to said actuating device comprising two mutilated gears connected with said actuating device and one with the other, each of said mutilated gears comprising two groups of teeth 80

arranged on opposite sides thereof, said gears being arranged in the same plane and so positioned relatively one to the other that when rotated the groups of teeth of each of 5 said gears will lie adjacent to the corresponding spaces between the groups of teeth of the other gear, and a toothed operating member arranged in the same plane with said mutilated gears and movable in two directions, whereby it will be caused to engage the teeth of one of said mutilated gears when moved in one direction and the teeth of the other of said mutilated gears when moved in the opposite direction, a locking 10 plate connected with and rotatable with one of said mutilated gears, and a plate secured to and movable with said operating member and arranged to coöperate with said locking plate to check the movement of said 15 actuating device when the operating member has passed out of engagement with said gear.

22. In a machine of the character described, the combination, with a counting device and an actuating device therefor, of mechanism for imparting movement to said actuating device comprising two mutilated gears connected with said actuating device and one with the other, each of said mutilated gears comprising two groups of teeth arranged on opposite sides thereof, said gears being arranged in the same plane and so positioned relatively one to the other that when rotated the groups of teeth of each of 30 said gears will lie adjacent to the corresponding spaces between the groups of teeth of the other gear, a segmental rack pivotally supported in substantially the same plane with said mutilated gears and so arranged 35 that when oscillatory movement is imparted thereto it will alternately engage the teeth of the respective mutilated gears, locking plates secured to and rotatable with the respective mutilated gears and each having 40 curved recesses in the opposite sides thereof, and segmental plates mounted on the axis of and movable with said operating member and so arranged that one of said segmental plates will enter one of the recesses of one 45 of said locking plates as said operating member moves out of engagement with the respective mutilated gear.

23. In a machine of the character described, the combination, with a counting device and an actuating device therefor, of mechanism for imparting movement to said actuating device comprising two mutilated gears connected with said actuating device and one with the other, each of said mutilated gears comprising two groups of teeth arranged on opposite sides thereof, said gears being arranged in the same plane and so positioned relatively one to the other that when rotated the groups of teeth of each of 60 said gears will lie adjacent to the corre-

sponding spaces between the groups of teeth of the other gear, a segmental rack pivotally supported in substantially the same plane with said mutilated gears and so arranged that when oscillatory movement is 70 imparted thereto it will alternately engage the teeth of the respective mutilated gears, locking plates secured to and rotatable with the respective mutilated gears and each having curved recesses in the opposite sides 75 thereof, and segmental plates mounted on the axis of and movable with said operating member and so arranged that one of said segmental plates will enter the recess in and engage the edge of one of said locking plates 80 as the operating member moves out of engagement with the gear connected with that plate, thereby imparting a slight further movement to said plate and its gear and locking the plate and its gear against further movement.

24. In a machine of the character described, the combination, with a rotary member, of mechanism for imparting rotatory movement to said member comprising two 90 mutilated gears mounted on parallel axes, each of said mutilated gears comprising two groups of teeth arranged on opposite sides thereof, said mutilated gears being arranged in the same plane and so positioned 95 relatively one to the other that when they are rotated in unison the teeth of each of said mutilated gears will pass through the corresponding space between the teeth of the other of said mutilated gears, inter- 100 meshing gears mounted to rotate about the axes of and rigidly secured to the respective mutilated gears, a segmental rack mounted on an axis arranged between the planes of the axes of said mutilated gears and having 105 oscillatory movement about said axis, whereby said segmental rack will engage the teeth of one of said mutilated gears as said rack moves in one direction and will engage the teeth of the other of said mutilated gears as said rack moves in the opposite direction, thereby imparting intermittent movement in the same direction to 110 said mutilated gears and said part to be rotated.

25. In a machine of the character described, a part to be rotated, and means for imparting to said part intermittent rotatory movements in the same direction comprising two mutilated gears connected one with 120 the other and rotatable in unison, each of said gears comprising two groups of teeth arranged on opposite sides thereof and said two gears being so positioned with relation one to the other that the two groups of teeth 125 of each gear will be arranged in a line intersecting the line of the two groups of teeth of the other gear, and a toothed operating member having movement in two directions, said toothed operating member being so ar- 130

ranged with relation to said mutilated gears that its movement in one direction will cause it to engage one of said gears and move said part to be rotated in one direction 5 and its movement in the opposite direction will cause it to engage the other of said gears and move said part to be rotated in the same direction said part was moved by the preceding movement of said operating 10 member.

26. In a machine of the character described, a plurality of aligned counting devices, an actuator arranged normally to actuate one of said counting devices and capable of movement into a neutral position with respect to all of said counting devices, and a rotatory cam for moving said actuator into its operative or its neutral position.

27. In a machine of the character described, a plurality of aligned counting devices, an actuator adapted to be moved into operative relation with any one of a plurality of said counting devices or into a neutral position with respect to all of said 25 counting devices, a setting shaft mounted in said machine, means outside of said machine to rotate said setting shaft, and a connection between said setting shaft and said actuator to cause the latter to be actuated by the rotary movement of said shaft.

28. In a machine of the character described, a plurality of aligned counting devices, an actuator shaft extending substantially parallel with the axis of said counters, 35 an actuator mounted on said actuator shaft and adapted to be moved into operative relation with any one of a plurality of said counting devices or into a neutral position with respect to all of said counting devices, 40 a second shaft arranged substantially parallel with said actuator shaft, a carrier mounted on said second shaft, connected with said actuator and having a projection thereon, a setting shaft, and a cam mounted 45 on said setting shaft and having a groove to receive said projection, said cam groove being shaped to move said actuator into any one of its operative positions or into its neutral position.

50 29. In a machine of the character described, a plurality of aligned counting devices, a plurality of actuators, each of which is adapted to be moved into operative relation with one of said counting devices or into 55 a neutral position with respect to all of said counting devices, a setting shaft, a plurality of cams mounted on said setting shaft, and connections between said cams and the respective actuators, whereby the rotation of 60 said setting shaft will simultaneously move the several actuators into and out of their neutral positions.

30. In a machine of the character described, the combination, with a counting device, an actuator therefor, and means for

operating said actuator comprising a movable member, of a locking member rigidly secured to and movable with said operating member, a second locking member movably mounted on a fixed part of said machine, 70 means tending to hold said second locking member normally in the path of the first-mentioned locking member, and key controlled means for moving said second locking member into and retaining the same in 75 an inoperative position.

31. In a machine of the character described, the combination, with a counting device, an actuator therefor, and means for operating said actuator comprising a movable member, of a locking member rigidly connected with said movable member, a locking arm movable into and out of the path of said locking member, a tripping finger connected with said locking arm, a detent arm 80 adapted to hold said locking arm normally in the path of said locking member, a tripping finger connected with said locking arm, and means for actuating first the last-mentioned tripping finger and then the first- 85 mentioned tripping finger.

32. In a machine of the character described, the combination, with a counting device, an actuator therefor, and means for operating said actuator comprising a movable member, of a locking member rigidly connected with said movable member, a locking arm movable into and out of the path of said locking member, means for retaining 90 said locking arm in the path of said locking member, and means for first releasing said retaining means and then actuating said locking arm to move it out of the path of said locking member.

33. In a machine of the character described, the combination, with a counting device, an actuator therefor, and means for operating said actuator comprising a movable member, of a locking member rigidly connected with said movable member, a locking 105 arm movable into and out of the path of said locking member, a tripping finger connected with said locking arm, a detent arm adapted to hold said locking arm normally in the path of said locking member, a tripping 110 finger connected with said locking arm, a key barrel extending from the exterior of said machine to a point adjacent to said tripping fingers and having transverse slots to receive the same when said locking arm is 115 in its locking position, the slot for the first-mentioned tripping finger being arranged nearer the outer end of said key barrel than is the slot for the last-mentioned tripping finger, a key adapted to enter said key barrel 120 and shaped to engage the last-mentioned tripping finger before it engages the first-mentioned tripping finger, and springs tending 125 to hold said tripping fingers normally in said slots.

34. In a machine of the character described, the combination, with a counting device, an actuator therefor, and means for operating said actuator comprising a movable member, of a locking member rigidly connected with said movable member, a locking arm movable into and out of the path of said locking member, a tripping finger connected with said locking arm, a detent arm 5 adapted to hold said locking arm normally in the path of said locking member, a tripping finger connected with said locking arm, a key barrel extending from the exterior of said machine to a point adjacent to said 10 tripping fingers and having transverse slots to receive the same when said locking arm is in its locking position, the slot for the first-mentioned tripping finger being arranged nearer the outer end of said key barrel than is 15 the slot for the last-mentioned tripping finger, and a key adapted to enter said key barrel and having longitudinal grooves to receive the ends of respective tripping fingers, said 20 grooves having tapered outer ends and that groove which is adapted to receive the last-mentioned tripping finger being of less 25 length than the groove which is adapted to receive the first-mentioned tripping finger, and springs tending to hold said tripping 30 fingers normally in the respective slots in said key barrel.
35. In a machine of the character described, the combination, with a counting device, an actuator therefor, and means for operating said actuator comprising a movable member, of a locking member rigidly connected with said movable member, a locking arm movable into and out of the path of said locking member, a tripping 35 finger connected with said locking arm, a detent arm adapted to hold said locking arm normally in the path of said locking member, a tripping finger connected with said locking arm, a key barrel extending from the exterior of said machine to a point adjacent to said 40 tripping fingers and having transverse slots to receive the same when said locking arm is in its locking position, the slot for the first-mentioned tripping finger being arranged nearer the outer end of said key barrel than is the slot for the last-mentioned tripping finger, a key adapted to enter said key barrel and shaped to engage the last-mentioned tripping finger before it engages 45 the first-mentioned tripping finger, a type plate carried by said key, and springs tending to hold said tripping fingers normally in said slots.
36. In a machine of the character described, the combination, with a counting device, an actuator therefor, and operating mechanism for said actuator comprising an oscillating operating member, and a plate rigidly connected with said operating member, of an arm pivotally mount- 50 ed on a fixed part of said machine and movable into and out of the path of said plate, a pin carried by said arm, a spring tending to hold said arm normally in the path of said plate, a second arm arranged to engage 55 said pin and retain said locking arm in the path of said plate, a spring to hold said retaining arm normally in engagement with said pin, tripping fingers rigidly connected with said locking arm and said retaining arm, respectively, a key barrel arranged adjacent to said arms and having transverse slots to receive the respective tripping fingers, the slot for the tripping finger of the retaining arm being farther removed 60 from the outer end of said key barrel than is the other slot, and a key having longitudinal grooves arranged to receive those portions of the respective tripping fingers which extend into said key barrel, said slots 65 having tapered outer ends and that slot adapted to receive the tripping finger of the retaining arm being of less length than the other slot.
37. In a machine of the character described, the combination with a counting device, an actuator therefor, and operating mechanism for said actuator comprising a locking member, of a second locking member movable into and out of the path of the first-mentioned locking member, means for controlling the position of said second locking member, a key to actuate said controlling means, and a type plate carried by said key.
38. In a machine of the character described, the combination, with a counting device, an actuator therefor, and operating mechanism for said actuator, of a locking member connected with said operating mechanism, a second locking member co-operating with the first-mentioned locking member to control the movement of said operating mechanism, and key-actuated means to control said second locking member.
39. In a machine of the character described, the combination, with a counting device, an actuator therefor, and operating mechanism for said actuator, of a locking member connected with said operating mechanism, a second locking member co-operating with the first-mentioned locking member to control the movement of said operating mechanism, key-actuated means to control said second locking member, and a key to actuate said controlling means, said key having an indentifying device.
40. In a machine of the character described, the combination, with a counting device, an actuator therefor, a rotatory operating mechanism for said actuator, a locking member connected with and rotating in unison with said operating mechanism, a second locking member co-operating with the first-mentioned locking member to control the

movement of said operating mechanism, and key-actuated means to control said second locking member.

41. In a machine of the character described, the combination, with a plurality of counting devices, an actuator for said counting devices, setting means for said actuator comprising a shaft, and operating mechanism for said actuator comprising an oscillating segmental plate, of a star wheel rigidly secured to the shaft of said setting means, and a pawl pivotally mounted in the path of said segmental plate and having a nose adapted to enter one of the spaces between the teeth of said star wheel when said pawl is actuated by the oscillation of said segmental plate.

42. In a machine of the character described, the combination, with a plurality of counting devices, an actuator, setting mechanism for said actuator comprising a shaft, a star wheel secured to said shaft, actuating mechanism for said actuator comprising a segmental plate pivotally mounted on a fixed part of said machine, of a pawl pivotally mounted on a fixed part of said machine having a nose adapted to enter the space between two of the teeth on said star wheel, and a tapered portion lying adjacent to said segmental plate, whereby the movement of said segmental plate about its pivotal center will move said pawl into engagement with said star wheel, the point of contact between said pawl and said segmental plate being substantially in line with said pawl and its pivotal support, whereby the force of the contact between the pawl and the plate will be exerted upon the support for said pawl.

43. In a machine of the character described, the combination, with a plurality of counting devices, an actuator therefor having a neutral position, setting mechanism for said actuator comprising a shaft, a star wheel rigidly secured to said shaft, and operating mechanism for said actuator comprising a segmental plate pivotally mounted on a fixed part of said machine, of a pawl arranged in the path of said segmental plate and having a nose adapted to enter one of the spaces between the teeth of said star wheel, said star wheel having a wide tooth so arranged thereon that when said actuator is in its neutral position said wide tooth will lie in the path of the nose of said pawl and said pawl will be held in the path of said segmental plate, thereby locking said operating mechanism against movement.

44. In a machine of the character described, the combination with a plurality of counting devices, an actuator therefor having a neutral position, and operating mechanism for said actuator, of means for locking said operating mechanism against op-

erative movement when said actuator is in its neutral position.

45. In a machine of the character described, the combination, with printing counters, an electrotype plate, and a platen adapted to be moved in the same direction to print either from said printing counters or from both said printing counters and said electrotype plate, of an actuating device for said platen, and devices to positively determine the amount of movement imparted to said platen.

46. In a machine of the character described, the combination, with a series of aligned printing counters, an electrotype plate arranged adjacent to said printing counters, a printing carriage movably mounted adjacent to said printing counters and said electrotype plate, a platen mounted on said carriage, and means for imparting to said carriage movements in the same direction but of different lengths, one of said movements being sufficient to print from both the printing counters only and the other of said movements being sufficient to print from both the printing counters and the electrotype plate.

47. In a machine of the character described, the combination, with a series of aligned printing counters, an electrotype plate, and a platen capable of movement in the same direction to print from said printing counters or from said printing counters and said electrotype plate, of an operating device for imparting movement to said platen, and means to positively control the movement of said device and thus regulate the amount of movement imparted to said platen.

48. In a machine of the character described, the combination, with a series of aligned printing counters, an electrotype plate, and a platen capable of movement in the same direction to print from said printing counters or from said printing counters and said electrotype plate, of an operating device to impart movement to said platen, said operating device being capable of movement in one direction to cause said platen to engage said printing counters only and of movement in the opposite direction to cause said platen to engage both said printing counters and the electrotype plate.

49. In a machine of the character described, the combination, with a series of aligned printing counters, an electrotype plate, and a platen capable of movement in the same direction to print from said printing counters or from said printing counters and said electrotype plate, of an operating device to impart movement to said platen, said operating device being capable of movement in one direction to cause said platen to engage said printing counters only and of movement in the opposite direction to cause

said platen to engage both said printing counters and the electrotype plate, and positive locking devices to control the direction of movement of said operating device.

- 5 50. In a machine of the character described, the combination, with printing counters to record and print a trip record, an accumulator to record a total record, means for transferring said total record to 10 said printing counters, and a platen to print either the trip record or the total record from said printing counters, of means for operating said platen to print either of said records, and means to prevent the operation 15 of said platen to print a total record before the count has been transferred from said accumulator to said printing counters.
51. In a machine of the character described, the combination, with printing 20 counters to record and print a trip record, an accumulator to record a total record, means for transferring said total record to said printing counters, and a platen to print either the trip record or the total record 25 from said printing counters, of means for operating said platen to print either of said records, and means to prevent the operation of said platen to print a trip record after the total count has been transferred from 30 the accumulator to the printing counters.

52. In a machine of the character described, the combination, with printing counters to record and print a trip record, an accumulator to record a total record, 35 means for transferring said total record to said printing counters, and a platen to print either the trip record or the total record from said printing counters, of an operating device for said platen movable in one 40 direction to print a total record and movable in the opposite direction to print a trip record, and means controlled by the transferring of the count from said accumulator to said printing counters to determine the 45 direction of movement of said operating device.

53. In a machine of the character described, the combination, with printing counters to record and print a trip record, 50 an accumulator to record a total record, means for transferring the count from said accumulator to said printing counters, a platen, and means to impart a short movement to said platen to cause a trip record to 55 be printed, and a longer movement to cause a total record to be printed, of means controlled by the transferring of the count from said accumulator to said printing counters to determine the length of the 60 movement imparted to said platen.

54. In a machine of the character described, the combination, with printing counters to record and print a trip record, means for resetting said printing counters, 65 an accumulator adapted to record a total

record, means for resetting said accumulator to transfer the record therefrom to said printing counters, and a platen capable of a short movement to print a trip record from said printing counters and of a longer 70 movement to print a total record from said printing counters, of a device for actuating said platen, and means controlled by the resetting of said accumulator to control the amount of movement imparted to said 75 platen.

55. In a machine of the character described, the combination, with printing counters to record and print a trip record, means for resetting said printing counters, 80 an accumulator adapted to record a total record, means for resetting said accumulator to transfer the record therefrom to said printing counters, and a platen capable of a short movement to print a trip record 85 from said printing counters and of a longer movement to print a total record from said printing counters, of an operating device for said platen movable in one direction to impart a short movement thereto and movable 90 in the opposite direction to impart a longer movement thereto, and a locking device, the position of which is controlled by the resetting of said accumulator, to determine the direction of movement of said operating device. 95

56. In a machine of the character described, the combination with printing counters to record and print a trip record, means for resetting said printing counters, 100 an accumulator adapted to record a total record, means for resetting said accumulator to transfer the record therefrom to said printing counters, and a platen capable of a short movement to print a trip record 105 from said printing counters and of a longer movement to print a total record from said printing counters, of an operating handle pivotally mounted on said machine, a connection between said platen and said 110 handle, two segmental plates connected to said handle and arranged in different planes, disks having parts adapted to be moved into and out of the path of the respective segmental plates, and means controlled by the resetting of said accumulator 115 to determine the positions of said disks.

57. In a machine of the character described, the combination, with printing counters to record and print a trip record, 120 means for resetting said printing counters, an accumulator adapted to record a total record, means for resetting said accumulator to transfer the record therefrom to said printing counters, and a platen capable of 125 a short movement to print a trip record from said printing counters and of a longer movement to print a total record from said printing counters, of an operating handle pivotally mounted on said machine, a con- 130

nection between said platen and said handle, two segmental plates connected to said handle and arranged in different planes, two disks arranged in the same planes with the respective segmental plates and rigidly connected one to the other, each disk having a cut away portion adapted to be moved into or out of alinement with its segmental plate, a gear connected with said disks, and a gear connected with said accumulator and meshing with the first-mentioned gear to impart movement to said disks, when said accumulator is reset to zero.

58. In a machine of the character described, the combination, with printing counters to record and print a trip record, means for resetting said printing counters, an accumulator adapted to record a total record, means for resetting said accumulator to transfer the record therefrom to said printing counters, and a platen capable of a short movement to print a trip record from said printing counters and of a longer movement to print a total record from said printing counters, of a handle pivotally mounted on said machine and movable in one direction to impart a short movement to said platen and movable in the opposite direction to impart a longer movement to said platen, two segmental plates secured to and movable with said handle and arranged in different planes, two disks rigidly connected one to the other and arranged in the same plane with the respective segmental plates, each of said disks having a cut away portion, the cut away portions of the respective disks being arranged in different positions relatively to the body of the disk, means actuated by the recording of the first fare to move the recess of one of said disks into alinement with its segmental plate and permit the handle to be moved in a direction to impart a short movement to said platen, and means actuated by the resetting of said actuator to move the cut away portion of the other disk into alinement with its segmental plate to permit the handle to be moved in the other direction to impart a longer movement to the platen and to move the first-mentioned disk into a position to prevent the movement of the handle to impart a short movement to the platen.

59. In a machine of the character described, the combination, with printing counters, an actuator therefor, an accumulator, means for resetting said accumulator to transfer the count therefrom to said printing counters, an electrotype plate adjacent to said printing counters, a platen capable of a short movement to print from said printing counters only and of a longer movement to print from both the printing counters and the electrotype plate, of an operating handle pivotally mounted on said machine and connected with said platen, said handle being adapted to move in one direction to print a detail record or a total record, and actuating mechanism for said

handle being adapted to move in one direction to impart a short movement to said platen and to move in the opposite direction to impart a longer movement thereto, segmental plates secured to and movable with said handle, disks arranged in the same plane with respect to the segmental plates and having recesses adapted to be moved into and out of alinement with the respective plates, a one-toothed gear connected with said disks, an actuating device connected with said actuator to move said gear and said disk through one space upon the first operation of said actuator, a nine-toothed gear connected with said disk, and a gear connected with said accumulator and meshing with said nine-toothed gear to move said disks through nine spaces when said accumulator is reset to zero.

60. In a machine of the character described, the combination, with printing counters, an actuator therefor, an accumulator, means for resetting said accumulator to transfer the count therefrom to said printing counters, an electrotype plate adjacent to said printing counters, a platen capable of a short movement to print from said printing counters only and of a longer movement to print from both the printing counters and the electrotype plate, of an operating handle pivotally mounted on said machine and connected with said platen, said handle being adapted to move in one direction to impart a short movement to said platen and to move in the opposite direction to impart a longer movement thereto, segmental plates secured to and movable with said handle, disks arranged in the same plane with the respective segmental plates and having recesses adapted to be moved into and out of alinement with the respective plates, a one-toothed gear connected with said disks and comprising a disk having a recess, one wall of which forms the tooth of the gear and another portion of which is curved inward, a two-toothed gear connected with said actuator adapted to engage said one toothed gear upon each half revolution of said actuator to advance said gear and said disks one space, each tooth of said two-toothed gear having a segmental edge to engage the curved recess in said one-toothed gear to prevent the overthrow of said disks, a nine-toothed gear secured to said disks, and a gear connected with said accumulator and meshing with said nine-toothed gear to move said disks through nine spaces when said accumulator is reset to zero.

61. In a machine of the character described, the combination, with printing counters, and a platen capable of two movements of different lengths in the same direction to print a detail record or a total record, and actuating mechanism for said

5 platen comprising a shaft having two gears mounted thereon, of a handle pivotally mounted on said machine and having two segmental gears connected thereto, one of said gears meshing with one of the gears on said shaft, idle gearing interposed between the other of said segmental gears and the second gear on said shaft, whereby the movement of said handle in either direction 10 will cause said shaft to rotate in a single direction.

62. In a machine of the character described, the combination, with printing counters, an accumulator, means for transferring the record from the accumulator to the printing counters, and a platen capable of two movements of different lengths in the same direction to print a detail record or a total record, and actuating mechanism for 15 said platen comprising a shaft having two gears mounted thereof, of a handle pivotally mounted on said machine and having two segmental gears connected thereto, one of said gears meshing with one of the gears on said shaft, idle gearing interposed between the other of said segmental gears and the second gear on said shaft, whereby the movement of said handle in either direction will cause said shaft to rotate in a single direction, and means controlled by the transferring of the record from said accumulator to said printing counters to determine the direction of movement of said handle. 20

63. In a machine of the character described, the combination, with printing counters, a platen capable of two movements of different lengths in the same direction to print a detail record or a total record, and actuating mechanism for said platen, comprising a shaft having two gears mounted thereon, of a handle pivotally mounted on said machine and having two segmental gears connected thereto, one of said gears meshing with one of the gears on said shaft, idle gearing interposed between the other of said segmental gears and the second gear on said shaft, whereby the movement of said handle in either direction will cause said shaft to rotate in a single direction and 25 means to lock the gears on said shaft against movement when said handle is in its idle position. 30

64. In a machine of the character described, the combination, with printing counters, a printing device capable of two movements of different lengths in the same direction to print different records, and actuating mechanism for said printing device, of a handle mounted on said machine and 35 capable of movement about its axis in either direction, and connections between said handle and said actuating mechanism to cause said printing device to be moved in the same direction when said handle is moved in either direction. 40

65. In a machine of the character described, the combination, with printing counters, a printing device capable of two movements of different lengths in the same direction to print different records, and actuating mechanism for said printing device, of a handle mounted on said machine and capable of movement about its axis in either direction, connections between said handle and said actuating mechanism to cause said printing device to be moved in the same direction when said handle is moved in either direction, and means controlled by the position of said handle to lock said actuating mechanism against movement. 45

66. In a machine of the character described, the combination, with printing counters, a platen capable of two movements of different lengths in the same direction to print a detail record or a total record, and actuating mechanism for said platen comprising a shaft having two gears mounted thereon, of a handle pivotally mounted on said machine and having two segmental gears connected thereto, one of said gears meshing with one of the gears on said shaft, idle gearing interposed between the other of said segmental gears and the second gear on said shaft, whereby the movement of said handle in either direction will cause said shaft to rotate in a single direction, and means controlled by the position of said handle to lock the gears on said shaft against movement when said handle is in its idle position. 50

67. In a machine of the character described, the combination, with printing counters, and a platen capable of two movements of different lengths in the same direction to print a detail record or a total record, and actuating mechanism for said platen comprising a shaft having two gears mounted thereon, of a handle pivotally mounted on said machine and having two segmental gears connected thereto, one of said gears meshing with one of the gears on said shaft, idle gearing interposed between the other of said segmental gears and the second gear on said shaft, whereby the movement of said handle in either direction will cause said shaft to rotate in a single direction, both of said segmental gears being out of mesh with their respective gears when said handle is in its idle position, a pin secured to the outer gear on said shaft, and an arm secured to one of said segmental gears and having a groove arranged to engage said pin when said handle is in its idle position. 55

68. In a machine of the character described, the combination, with printing counters, and a platen capable of two movements of different lengths in the same direction to print a detail record or a total record, and actuating mechanism for said platen comprising a shaft having two gears mount- 60

- ed thereon, of a handle pivotally mounted on said machine and having two segmental gears connected thereto, one of said gears meshing with one of the gears on said shaft, 5 idle gearing interposed between the other of said segmental gears and the second gear on said shaft, whereby the movement of said handle in either direction will cause said shaft to rotate in a single direction, both of 10 said segmental gears being out of mesh with their respective gears when said handle is in its idle position, a pin secured to the outer gear on said shaft, and an arm secured to one of said segmental gears and having a 15 cam shaped groove adapted to engage said pin as said handle approaches its idle position and slightly advance said gear.
69. In a machine of the character described, the combination, with a printing 20 mechanism comprising a shaft capable of a plurality of movements of different lengths in the same direction, and paper feeding rollers, of a plate pivotally mounted on said machine and having a cam slot extending 25 about the axis of said shaft, an arm carried by said shaft, a pin secured to said arm and extending into said cam slot, the shape of said slot being such that the amount of movement imparted to said cam plate is proportionate to the amount of rotation imparted to said shaft, a segmental rack secured to said cam plate, and a gear connected with one of said paper feeding rollers and meshing with said segmental rack.
- 30 70. In a machine of the character described, the combination, with printing mechanism comprising a shaft capable of a plurality of movements in the same direction but of different lengths, paper feeding 35 rollers, a gear rotatably mounted on the axis of one of said paper feeding rollers, a ratchet secured to said roller, an arm secured to said gear, and a pawl carried by said arm and meshing with said ratchet, of a plate pivotally mounted on said machine and having a cam slot arranged eccentrically to the axis of said shaft and having a straight portion extending from one end thereof, an arm secured to said shaft, a pin carried by said 40 45 arm and extending into said slot, and a segmental rack connected with said plate and meshing with the gear of said paper feeding roller.
- 50 71. In a machine of the character described, the combination, with printing 55 counters, an actuating device therefor, operating mechanism to impart movement to said actuating device, said operating mechanism comprising a rotatable shaft, and printing mechanism to take a record from said printing counters, said printing mechanism also comprising a rotatable shaft, of locking members secured to the respective shafts, and a device movably mounted adjacent to 60 65 said locking members and so arranged that the movement of either of said members from its normal position will cause said device to engage the other of said members to lock its shaft against movement.
72. In a machine of the character described, the combination with printing counters, an actuating device therefor, an operating mechanism to impart movement to said actuating device, said operating mechanism comprising a rotatable shaft, printing 75 mechanism to take a record from said printing counters, said printing mechanism also comprising a rotatable shaft, of a locking plate mounted on said operating shaft, an arm pivotally supported on said machine 80 and having one end arranged to be moved into and out of the path of said locking plate and provided at the other end with a nose, and a disk secured to said printing shaft and having a recess adapted to receive 85 the nose of said arm when said printing mechanism is in its normal position, the movement of said printing shaft and said disk serving to force said nose out of said recess and thus move the arm about its pivotal support and into the path of said locking plate.
73. In a machine of the character described, the combination, with printing 90 counters, an actuating device therefor, an operating mechanism to impart movement to said actuating device, said operating mechanism comprising a rotatable shaft, printing mechanism to take a record from 95 said printing counters, said printing mechanism also comprising a rotatable shaft, of a disk rigidly secured to said printing shaft and having a recess in the periphery thereof, an arm pivotally mounted between its ends on said machine and having on one side of 100 its pivotal center a nose adapted to enter said recess when said printing mechanism is in its normal position and to be moved out of said recess by the printing movement of said shaft, thereby imparting movement to 105 the opposite end of said arm, and a segmental plate rigidly secured to said operating shaft adapted to be moved into the path of the last-mentioned end of said arm during the movement of said operating mechanism.
74. In a machine of the character described, the combination, with printing 110 counters, an actuating device therefor capable of movement into and out of a neutral position, setting mechanism for said actuating device, and printing mechanism for taking a record from said printing counters, of means for locking said printing mechanism against movement at all times except when 115 said actuator is in its neutral position.
75. In a machine of the character described, the combination, with printing 120 counters, an actuating device therefor capable of movement into and out of a neutral 125 position, setting mechanism for said actuating device, and printing mechanism for taking a record from said printing counters, of means for locking said printing mechanism against movement at all times except when said actuator is in its neutral position.

position, setting mechanism for said actuating device, and printing mechanism for taking a record from said printing counters, of means for retaining said actuator in its neutral position during the operation of said printing mechanism.

76. In a machine of the character described, the combination, with printing counters, an actuating device therefor capable of movement into and out of a neutral position, setting mechanism for said actuating device, and printing mechanism for taking a record from said printing counters, of cooperating locking devices controlled by the position of said actuator and the operation of said printing mechanism to lock said printing mechanism against operation at all times except when said actuator is in its neutral position and also serving to retain said actuator in its neutral position during the operation of said printing mechanism.

77. In a machine of the character described, the combination, with printing counters, an actuator therefor, capable of movement into and out of neutral position, setting mechanism for said actuator comprising a rotatable shaft, and printing mechanism for taking a record from said printing counters and also comprising a rotatable shaft, of a disk secured to said printing shaft and having a recess, an arm pivotally mounted between its ends on said machine and having at one end a nose adapted to enter the recess in said disk and having at its other end a projection, a second arm pivotally mounted between its ends on said frame and having one end adapted to be moved into and out of the path of the projection on the first-mentioned arm and having at its other end a nose, a disk rigidly secured to said setting shaft and having a recess in its periphery, said recess being so arranged with relation to said setting shaft that when said actuator has been moved into a neutral position said recess will be in alignment with the nose on said second arm, and a spring tending to move said nose into said recess.

78. In a machine of the character described, the combination, with printing counters, and means for resetting said printing counters to zero, two accumulators movable into and out of operative relation with said printing counters, and printing mechanism to take a record from said printing counters, of means actuated by the movement of said printing mechanism for locking both of said accumulators against movement in operative relation with said printing counters during the operation of said printing mechanism.

79. In a machine of the character described, the combination, with printing counters, and means for resetting said printing

counters to zero, two accumulators movable into and out of operative relation with said printing counters, and printing mechanism to take a record from said printing counters, of means for locking said accumulators against movement into operative relation with said printing counters during the operation of said printing mechanism, and means controlled by the resetting of said printing counters to zero to release said accumulators, whereby they may be moved into operative relation with said printing counters.

80. In a machine of the character described, the combination, with printing counters, an accumulator movable into and out of operative relation with said printing counters, and printing mechanism to take a record from said printing counters, and means to actuate said printing mechanism, of a locking member movable into and out of locking relation with said accumulator, and means actuated by the movement of said actuating means for said printing mechanism to move said locking member into its operative position.

81. In a machine of the character described, the combination, with printing counters, means for resetting said printing counters to zero, an accumulator movable into and out of operative relation with said printing counters, printing mechanism to take a record from said printing counters, and means to actuate said printing mechanism, of a locking member movable into and out of operative relation with said accumulator, means actuated by the movement of said actuating means for said printing mechanism to move said locking member into its operative position, and means controlled by the resetting of said printing counters to zero to move said locking member into its inoperative position.

82. In a machine of the character described, the combination, with printing counters, and means for resetting said printing counters to zero, two accumulators movable into and out of operative relation with said printing counters, and printing mechanism to take a record from said printing counters, of two arms pivotally mounted on said machine and adapted to be moved into and out of the paths of the respective accumulators, said arms being connected one to the other and mounted on a common center, one of said arms extending beyond said center and having a nose, a rotatable disk operatively connected with said printing mechanism and having a recess arranged to receive said nose when said printing mechanism is in its normal position, whereby the operation of said printing mechanism will rotate said disk, force said nose out of said recess and move said arms into the paths of the respective accumulators.

83. In a machine of the character de-

scribed, the combination, with printing counters, and means for resetting said printing counters to zero, two accumulators movable into and out of operative relation with said printing counters, and printing mechanism to take a record from said printing counters, of two arms pivotally mounted on said machine and adapted to be moved into and out of the paths of the respective accumulators, said arms being connected one to the other and mounted on a common center, one of said arms extending beyond said center and having a nose, a rotatable disk operatively connected with said printing mechanism and having a recess arranged to receive said nose when said printing mechanism is in its normal position, whereby the operation of said printing mechanism will rotate said disk, force said nose out of said recess and move said arms into the paths of the respective accumulators, a detent to retain said arms in their locking positions, and means actuated by the resetting of said printing counters to zero to release said detent.

84. In a machine of the character described, the combination, with printing counters, and means for resetting said printing counters to zero, two accumulators movable into and out of operative relation with said printing counters, and printing mechanism to take a record from said printing counters, of two arms pivotally mounted on said machine and adapted to be moved into and out of the paths of the respective accumulators, said arms being connected one to the other and mounted on a common center, one of said arms extending beyond said center and having a nose, a rotatable disk operatively connected with said printing mechanism and having a recess arranged to receive said nose when said printing mechanism is in its normal position, whereby the operation of said printing mechanism will rotate said disk, force said nose out of said recess and move said arms into the paths of the respective accumulators, one of said arms having recesses in the edge thereof, a spring-pressed detent adapted to engage said recesses, a collar connected with the means for resetting said counters to zero, a projection carried by said collar, and a nose secured to one of said arms and arranged, when the arm is in its locking position, in the path of said projection, whereby the resetting of said printing counters to zero will cause the projection to engage the nose on said arm and move the arm into an inoperative position against the action of said spring-pressed detent.

85. In a machine of the character described, the combination, with printing counters, means for resetting said printing counters to zero comprising a rotatable part having a projection, printing mechanism to

take a record from said printing counters, and an actuating device for said printing mechanism having movement in two directions, of a pawl held normally in the path of said projection, and means actuated by the last movement of the actuating device for said printing mechanism to move said pawl out of the path of said projection.

86. In a machine of the character described, the combination, with printing counters, means for resetting said printing counters to zero comprising a rotatable part having a projection, printing mechanism to take a record from said printing counters, and an actuating device for said printing mechanism having movement in two directions, of a locking pawl held normally in the path of said projection, an arm connected with said locking pawl, a tripping pawl pivotally mounted on said arm, a spring tending to move said pawl in one direction, a stop to limit the movement of the pawl under the influence of said spring, and a part connected to and movable with said actuating device for said printing mechanism arranged to engage said pawl and pass the same on the first movement of said actuating device and to engage said pawl and actuate said arm upon the second movement of said actuating device to move said locking pawl out of the path of the nose on said projection.

87. In a machine of the character described, the combination, with printing counters, means for resetting said printing counters to zero comprising a rotatable part having a projection, printing mechanism to take a record from said printing counters, and an actuating device for said printing mechanism having movement in two directions, of a locking pawl held normally in the path of said projection, an arm connected with said locking pawl, a tripping pawl pivotally mounted on said arm, a spring tending to move said pawl in one direction, a stop to limit the movement of said pawl under the influence of said spring, and a part connected to and movable with said actuating device for said printing mechanism arranged to engage said pawl and pass the same on the first movement of said actuating device and to engage said pawl and actuate said arm upon the second movement of said actuating device to move said locking pawl out of the path of the nose on said projection, and means actuated by the resetting of said printing counters to zero to release said locking pawl and permit the same to be moved again into the path of said projection.

88. In a machine of the character described, the combination, with printing counters, means for resetting said printing counters to zero, and printing mechanism to take an impression from said printing

counters, of a device to prevent more than one impression being taken of each record made by said printing counters.

89. In a machine of the character described, the combination, with printing counters, means for resetting said printing counters to zero, and printing mechanism to take an impression from said printing counters, of a device to lock said printing mechanism against operation after one impression has been taken.

90. In a machine of the character described, the combination, with printing counters, means for resetting said printing counters to zero, and printing mechanism to take an impression from said printing counters, of a device to lock said printing mechanism against operation after one impression has been taken, and means controlled by the resetting to zero of said printing counters to release said locking device.

91. In a machine of the character described, the combination, with printing counters, means for resetting said printing counters to zero, and printing mechanism to take an impression from said printing counters, of a rotatable part connected with said printing mechanism and having a shoulder, a locking pawl mounted on a fixed part of said machine and adapted to be moved into the path of said shoulder, a spring to hold said pawl normally out of the path of said shoulder, means controlled by the operation of said printing mechanism to cause said pawl to be moved into the path of said shoulder at the end of the operation of said printing mechanism, and means actuated by the resetting of said printing counters to release said pawl to permit the same to be withdrawn from the path of said shoulder.

92. In a machine of the character described, the combination, with printing counters, means for resetting said printing counters to zero, and printing mechanism to take an impression from said printing counters, of a rotatable disk secured to said printing mechanism and having a recess in the periphery thereof, a pawl pivotally mounted on a fixed part of said machine and adapted to enter said recess when said printing mechanism is in its normal position, a lever pivotally mounted on said machine, a spring to move said lever in one direction about its pivotal center, means actuated by the operation of said printing mechanism to move said lever against the tension of said spring, a connection between said pawl and said lever to cause said pawl to be moved into an inoperative position when said lever moves under the tension of the spring, and a resilient connection between said pawl and said lever to cause both to be moved into engagement with the periphery of said disk when said printing mechanism has been

moved out of its normal position, whereby said pawl will be caused to enter said recess when said printing mechanism is returned to its normal position, and means controlled by the resetting of said printing counters to release said lever and permit the same and said pawl to move under the influence of said spring, thereby releasing said printing mechanism.

93. In a machine of the character described, the combination, with printing counters, means to reset said printing counters to zero, and printing mechanism to take a record from said printing counters, of means to prevent the resetting of said printing counters when said printing mechanism is out of its normal position.

94. In a machine of the character described, the combination, with printing counters, means to reset said printing counters to zero, and printing mechanism to take a record from said printing counters, of a rotatable disk connected with said printing mechanism and having a recess in the periphery thereof, an arm pivotally mounted on said machine and having a part arranged to enter said recess when said printing mechanism is in its normal position and to engage the periphery of said disk when said printing mechanism is out of its normal position, a rotatable disk connected with the resetting means for said printing counters and having a notch in the periphery thereof, said arm also having a part adapted to enter the recess in the disk of the resetting mechanism when said arm is in engagement with the disk of the printing mechanism.

95. In a machine of the character described, the combination, with a counting device, an accumulator adapted to be moved into and out of operative relation with said counting device, and an actuator to impart movement to said counting device to cause the same to record an item, of means actuated by the first operation of said actuator to lock said accumulator out of operative relation with said counting device.

96. In a machine of the character described, the combination, with a counting device, means for resetting said counting device to zero, an accumulator adapted to be moved into and out of operative relation with said counting device, and an actuator to impart movement to said counting device, to cause the same to record an item, of means actuated by the first operation of said actuator to lock said accumulator out of operative relation with said counting device, and means controlled by the resetting of said counting device to zero to render said locking means inoperative.

97. In a machine of the character described, the combination, with a counting device, means for resetting said counting device to zero, an accumulator adapted to be

5 moved into and out of operative relation with said counting device, and an actuator to impart movement to said counting device to cause the same to record an item, of co-
10 operating parts connected with said counting device and said accumulator, respectively, a device operated in unison with said actuator, means adapted to be engaged by said device upon its first operation to move said parts into alinement, said means being of such a character that the further operation of said device will not affect the positions of said parts.

98. In a machine of the character de-
15 scribed, the combination, with a counting device, means for resetting said counting device to zero, an accumulator adapted to be moved into and out of operative relation with said counting device, and an actuator
20 to impart movement to said counting device to cause the same to record an item, of co-operating parts connected with said counting device and said accumulator, respectively, a device operated in unison with said
25 actuator, means adapted to be engaged by said device upon its first operation to move said parts into alinement, said means being of such a character that the further operation of said device will not affect the positions of said parts, and means actuated by the resetting of said counting device to zero to move one of said parts out of alinement with the other of said parts.

99. In a machine of the character de-
35 scribed, the combination, with a resetting shaft, a plurality of counter wheels mounted upon said shaft, an accumulator comprising a shaft movable toward and away from said resetting shaft, an actuator shaft, and an
40 actuator mounted thereon, of a mutilated gear mounted upon said resetting shaft, a mutilated gear mounted upon said accumulator shaft, said mutilated gears having teeth adapted to be moved into and out of alinement, and means actuated by the operation of said actuator shaft to move said teeth into alinement.

100. In a machine of the character de-
50 scribed, the combination, with a resetting shaft, a plurality of counter wheels movable toward and away from said resetting shaft, an actuator shaft, and an actuator mounted thereon, of a mutilated gear mounted upon said resetting shaft, a mutilated gear mounted upon said accumulator shaft, said mutilated gears having teeth adapted to be moved into and out of alinement, means actuated by the operation of said actuator shaft to move said teeth into alinement, and means
55 actuated by the rotation of said resetting shaft to move said tooth of the mutilated gear carried by said resetting shaft out of alinement with said teeth of the mutilated gear on said accumulator shaft.

65 101. In a machine of the character de-

scribed, the combination, with a counter shaft, counting devices mounted on said counter shaft, means actuated by the rotation of said counter shaft to reset said counting devices to zero, an accumulator 70 shaft, accumulating devices mounted on said shaft, an actuator shaft, and an actuator mounted on said shaft to actuate said counting devices and said accumulating devices, of an actuating device mounted on and rotatable with said actuator shaft, a mutilated gear having a tooth arranged to be engaged by said actuating device on the first movement thereof and having a space arranged beyond said tooth, whereby the further operation of said actuating device will not affect the position of said mutilated gear, a mutilated gear mounted upon said accumulator shaft, having a tooth adapted to be engaged by said actuating device upon the 85 first operation thereof and also having a space lying beyond said tooth, whereby the further operation of said actuating device will not affect the position of said mutilated gear, the mutilated gear on said counter 90 shaft having a tooth adapted to be moved into alinement with a tooth of the mutilated gear on said accumulator shaft, and means actuated by the rotation of said resetting shaft to move said tooth of said mutilated gear on said counter shaft out of alinement with the tooth of the mutilated gear on said accumulator shaft.

102. In a machine of the character de-
scribed, the combination, with counting de-
100 vices, means for resetting said counting devices to zero, a plurality of accumulators each movable into and out of operative relation with said counting devices, and an actuator to actuate said counting devices and 105 said accumulators, of co-operating locking devices for locking said accumulators into inoperative relations to said counting devices, and means actuated upon the first movement of said actuator to move said 110 locking devices into operative positions.

103. In a machine of the character de-
scribed, the combination, with counting de-
115 vices, means for resetting said counting devices to zero, a plurality of accumulators each movable into and out of operative relation with said counting devices, and an actuator to actuate said counting devices and said accumulators, of co-operating locking devices for locking said accumulators in 120 inoperative relations to said counting devices, means actuated upon the first movement of said actuator to move said locking devices into operative positions, and means actuated by the resetting of said counting 125 devices to zero to move said locking devices into inoperative positions.

104. In a machine of the character de-
scribed, a counter shaft, counting devices carried by said shaft, and means actuated 130

by the rotation of said counter shaft to reset said counting devices to zero, two accumulator shafts movable toward and away from said counter shaft, accumulating devices 5 mounted on said accumulator shafts, and an actuator for actuating said counting devices and said accumulating devices, of a gear mounted on said counter shaft and having two locking teeth, a gear mounted on each 10 of said accumulator shafts and each having a locking tooth, and a device operated in unison with said actuator and arranged to actuate the gears on said counter shaft and said accumulator shafts upon the first operation 15 of said actuator to move the locking teeth of the gears on the accumulator shafts into alignment with the respective locking teeth of the gear on the counter shaft.

105. In a machine of the character described, a counter shaft, counting devices carried by said shaft, means actuated by the rotation of said counter shaft to reset said counting devices to zero, two accumulator shafts movable toward and away from 20 said counter shaft, accumulating devices mounted on said accumulator shafts, and an actuator for actuating said counting devices and said accumulating devices, of a gear mounted on said counter shaft and having 25 two locking teeth, a gear mounted on each of said accumulator shafts and each having a locking tooth, a device operated in unison with said actuator and arranged to actuate the gears on said counter shaft and said 30 accumulator shafts upon the first operation of said actuator to move the locking teeth of the gears on the accumulator shafts and into alignment with the respective locking teeth of the gear on the counter shaft, and means 35 actuated by the resetting of said counter shaft to move the locking teeth of the gear on said counter shaft out of alignment with the respective locking teeth of the gears on said accumulator shafts.

45 106. In a machine of the character described, a counter shaft, counting devices carried by said shaft, means actuated by the rotation of said counter shaft to reset said counting devices to zero, two accumulator 50 shafts movable toward and away from said counter shaft, accumulating devices mounted on said accumulator shafts, means actuated by the rotation of said accumulator shafts to reset the respective accumulating 55 devices to zero, and an actuator for actuating said counting devices and said accumulating devices, of a gear mounted on said counter shaft and having two locking teeth, and a gear mounted on each of said accumulator shafts and each having a locking tooth, a device operated in unison with said actuator and arranged to actuate the gears 60 on said counter shaft and said accumulator shafts upon the first operation of said actuator to move the locking teeth of the gears 65

on the accumulator shafts into alignment with the respective locking teeth of the gear on the counter shaft, means actuated by the resetting of said counter shaft to move the locking teeth of the gear on said counter shaft out of alignment with the respective locking teeth of the gears on said accumulator shafts, and means actuated by the rotation of one of said accumulator shafts, to reset its accumulating devices to zero, to move the locking teeth of the gear on said counter shaft into their locking positions. 70

107. In a machine of the character described, the combination, with counting devices, two accumulators each movable toward and away from said counting devices, separate means for resetting said counting devices and said accumulators to zero, and an actuator to actuate said counting devices and said accumulators, of means actuated 80 on the first operation of said actuator to lock said accumulators against movement toward said counting devices, and means actuated by the resetting of said counting devices to zero to release said locking means. 85

108. In a machine of the character described, the combination, with a counting device, two accumulators, each movable toward and away from said counting device, means for independently resetting said 95 counting device and said accumulators to zero, and a device to actuate said counting devices and said accumulators, of means actuated by the operation of said actuating device to lock said accumulators against 100 movement toward said counting device.

109. In a machine of the character described, the combination, with a counting device, two accumulators, each movable toward and away from said counting device, means for independently resetting said 100 counting device and said accumulators to zero, and a device to actuate said counting devices and said accumulators, of means actuated by the operation of said actuating 110 device to lock said accumulators against movement toward said counting device, and means to release said locking means.

110. In a machine of the character described, the combination, with a counting 115 device, two accumulators, each movable toward and away from said counting device, means for independently resetting said counting device and said accumulators to zero, and a device to actuate said counting 120 device and said accumulators, of means actuated by the operation of said actuating device to lock said accumulators against movement toward said counting device, and means actuated by the resetting of said 125 counting device to zero to release said locking means.

111. In a machine of the character described, the combination, with a counting device, two accumulators, each movable to- 130

ward and away from said counting device, means to independently reset said counting device and said accumulators to zero, a device to actuate said counting device and said 5 accumulators, of means actuated by the resetting of one of said accumulators to zero to lock the other accumulator against movement toward said counting device.

112. In a machine of the character described, the combination, with a counting device, two accumulators, each movable toward and away from said counting device, means to independently reset said counting device and said accumulators to zero, a device 10 to actuate said counting device and said accumulators, of means actuated by the operation of said actuating device to lock both of said accumulators against movement toward said counting device, means 15 actuated by the resetting of said counting device to zero to release said locking means, and means actuated by the resetting of one of said accumulators to zero to lock the other accumulator against movement toward 20 said counting device.

113. In a machine of the character described, the combination, with a counting device, two accumulators, each movable toward and away from said counting device, means 30 to independently reset said counting device and said accumulators to zero, a device to actuate said counting device and said accumulators, of means actuated by the resetting of one of said accumulators to zero to lock the other accumulator against movement toward 35 said counting device, and means for releasing said locking means by again resetting said counting device to zero.

114. In a machine of the character described, the combination, with counting devices, two accumulators each movable toward and away from said counting devices, separate means for resetting said counting devices and said accumulators to zero, and 40 an actuator to actuate said counting devices and said accumulators, of means actuated on the first operation of said actuator to lock said accumulators against movement toward said counting devices, means actuated by the 45 resetting of said counting devices to zero to release said locking means, and means actuated by the resetting of one of said accumulators to zero to lock the other accumulator against movement toward 50 said counting devices.

115. In a machine of the character described, the combination, with counting devices, two accumulators each movable toward and away from said counting devices, separate 55 means for resetting said counting devices and said accumulators to zero, and an actuator to actuate said counting devices and said accumulators, of means actuated on the first operation of said actuator to lock 60 said accumulators against movement toward 65 said counting devices.

said counting devices, means actuated by the resetting of said counting devices to zero to release said locking means, and means actuated by the resetting to zero of either of said accumulators to lock the other accumulator 70 against movement toward said counting devices, said locking means being released by again resetting said counting devices to zero.

116. In a machine of the character described, the combination, with a counting 75 device, and two accumulators, each of which is capable of movement into and out of operative relation with said counting device, and means for separately resetting said accumulators to zero, of a locking device to 80 prevent one of said accumulators from being moved into operative relation with said printing counters until the other of said accumulators has been moved into operative relation with said counting device and reset 85 to zero.

117. In a machine of the character described, the combination, with a counting device, and two accumulators, each of which is capable of movement into and out of 90 operative relation with said counting device, and means for separately resetting said accumulators to zero, of a disk carried by one of said accumulators, a second disk mounted in the plane with said first-mentioned disk 95 and having a recess in one side thereof to permit the first-mentioned disk and its accumulator to be moved toward the recessed disk and counting devices when the recess for the last-mentioned disk is adjacent to 100 the first-mentioned disk, and means actuated by the resetting of the other accumulator to control the position of said recessed disk.

118. In a machine of the character described, the combination, with a counting 105 device, and two accumulators, each of which is capable of movement into and out of operative relation with said counting device, and means for separately resetting said accumulators to zero, of a disk carried by 110 one of said accumulators, a second disk mounted in the plane with said first mentioned disk and having a recess in one side thereof, to permit the first-mentioned disk and its accumulator to be moved toward the 115 second disk and the counting device when the recess in the second disk is adjacent to the first-mentioned disk, a gear connected with said recessed disk, and a second gear secured to the other accumulator and adapted 120 to mesh with the first-mentioned gear when said accumulator is moved into operative relation with said counting device, whereby the resetting of said accumulator will impart a rotary movement to said recessed disk. 125

119. In a machine of the character described, the combination, with a counting device and two accumulators each adapted to be moved into operative relation with said counting device, an actuator to actuate said 130

counting device and said accumulators, and means to separately reset said accumulators to zero, of a disk connected with one of said accumulators, a second disk arranged in the 5 plane of the first-mentioned disk and adapted normally to prevent the movement of said first-mentioned disk and its accumulator toward said counting device, said second disk having a recess which, when adjacent 10 to the first-mentioned disk, will permit of the movement of said disk toward said counting device, means actuated by the resetting of the other accumulator to move the recess of said recessed disk into alignment with the first-mentioned disk, and 15 means operating in unison with said actuator to actuate said recessed disk to move its recess out of alignment with the first-mentioned disk.

20 120. In a machine of the character described, the combination, with printing counters, printing mechanism to take a record from said printing counters, two accumulators each movable into operative relation 25 with said printing counters to transfer their records thereto, means for separately resetting said printing counters and said accumulators to zero, and an actuator to cause said printing counters and said accumulators to record an item, of means actuated upon the first operation of said actuator to lock both accumulators out of operative relation with said printing counters, said locking means being moved into an inoperative 30 position by the resetting of said printing counters to zero, means to lock said printing counters against resetting to zero, and means actuated by said printing mechanism to release said resetting lock, means to lock one 35 of said accumulators against movement into operative relation with said printing counters, and means actuated by the resetting of the other accumulator to release said last-mentioned locking means and permit the 40 first-mentioned accumulator to be moved into operative relation with said printing counters, thereby making it necessary to take a record first from the printing counters, then 45 from the last-mentioned accumulator and third from the first-mentioned accumulator.

50 121. In a machine of the character described, the combination, with a counting device, two accumulators, and means to separately transfer the counts of said accumulators to said counting device, of a locking device to prevent the count of one accumulator being transferred to said counting device until the count of the other accumulator has been transferred to said counting 55 device.

60 122. In a machine of the character described, the combination, with a printing counter, two accumulators, and means to separately transfer the counts of said accumulators to said printing counter, of a lock-

ing device to prevent the count of one accumulator being transferred to said printing counter until the count of the other accumulator has been transferred to said printing counter, and a record taken from said printing counter. 70

123. In a machine of the character described, a detail counting device, a first totalizing device, a second totalizing device, means to actuate said counting devices and 75 said totalizing devices, means to separately reset said counting device and said totalizing devices to zero whereby separate records are preserved by the separate devices, and means to separately transfer records from said totalizing devices to said counting device. 80

124. In a machine of the character described, a detail counting device, a first totalizing device, a second totalizing device, means to actuate said counting device and 85 said totalizing devices, means to separately reset said counting device and said totalizing devices to zero whereby separate records are preserved by the separate devices, means to separately transfer records from said totalizing devices to said counting devices, and means to prevent the record of the second totalizing device being transferred to said counting device until the record of said first totalizing device has been transferred to 90 said counting device.

125. In a machine of the character described, a detail counting device, a printing device for taking a record from said counting device, a first totalizing device, a second 100 totalizing device, means to actuate said detail counting device and said totalizing devices, means to separately reset said counting device and said totalizing devices to zero, whereby separate records are preserved 105 by the respective devices, means to separately transfer the records from said totalizing devices to said counting device, and means to prevent the record of said second totalizing device from being transferred to 110 said detail counting device until the record of the first totalizing device has been transferred to said detail counting device and a record printed from said detail counting device. 115

126. In a machine of the character described, a detail counting device, a printing device for taking a record from said counting device, a first totalizing device, a second 120 totalizing device, means to actuate said detail counting device and said totalizing devices, means to separately reset said counting device and said totalizing devices to zero, whereby separate records are preserved by the respective devices, means to separately transfer the records from said totalizing devices to said counting device, and devices to prevent the record of the first totalizing device being transferred to said detail counting device until a record has been printed 125 130

from said detail counting device and to prevent the record of said second totalizing device from being transferred to said detail counting device until the record of said first 5 totalizing device has been transferred to said detail counting device and printed.

127. In a machine of the character described, the combination, with a counting device, an accumulator movable into and 10 out of operative relation with said counting device, an actuator, and a setting mechanism to move said actuator either into a position to actuate said counting device and said accumulator or into a neutral position, of a locking device controlled by said setting mechanism to prevent said accumulator from moving toward said counting device except when said actuator is in its neutral 15 position.
128. In a machine of the character described, the combination, with a counting device and two accumulators movable into and out of operative relation with said counting device, an actuator, and a setting 20 mechanism to move said actuator either into a position to actuate said counting device and said accumulators or into a neutral position, of a locking device controlled by said setting mechanism to normally prevent the 25 movement of either accumulator toward said counting device and to release both of said accumulators when said actuator has been moved into its neutral position.

129. In a machine of the character described, the combination, with a counting device, an accumulator movable into and out of operative relation with said counting device, an actuator, and a setting mechanism to move said actuator either into a position to actuate said counting device and 35 said accumulator or into a neutral position, of a strap connected with said accumulator and having a transverse lip, a disk rotatably connected with said setting mechanism and having a notch to receive said lip, said notch being so arranged with relation to said setting mechanism that when said actuator is moved into its neutral position said notch will be moved into alinement with said lip.
130. In a machine of the character described, the combination, with a counting device, two accumulators each movable toward and away from said counting device, an actuator, and setting mechanism, comprising a shaft, to move said actuator either 45 into operative relation with said counting device and said accumulators or into a neutral position, of straps connected with said accumulators and having lips, a disk secured to said setting shaft, a gear connected with 55 said disk, a second disk rotatably mounted adjacent to said setting shaft, and a gear connected to said disk and meshing with the first-mentioned gear, said disks being provided with recesses arranged to be moved 60

into the path of the lips of the respective straps when said actuator has been moved into its neutral position.

131. In a machine of the character described, the combination, with a counting device, operating mechanism to cause said counting device to record an item, and indicating counters, of a direct connection between said operating mechanism and the units indicating counter, whereby said 75 counter will be advanced one point upon each operation of said operating mechanism.

132. In a machine of the character described, the combination, with a counting device, operating mechanism to cause said 80 counting device to record an item, and indicating counters, of a gear connected with the units indicating counter and having the outer ends of its teeth concave, a two-toothed driving gear connected with said 85 operating mechanism, arranged to actuate the gear of said units indicating counter and having convex portions in the rear of its teeth arranged to engage the concave teeth of said first-mentioned gear to prevent 90 the overthrow of said indicating counter and having a recess in the front of each tooth to permit of the rotation of the first-mentioned gear when the two toothed gear is in its idle position. 95

133. In a machine of the character described, the combination, with a counting device, operating mechanism to cause said counting device to record an item, indicating counters, and means to separately reset 100 to zero said counting device and said indicating counters, of means to lock said operating mechanism against operation while said indicating counters are being reset to zero. 105

134. In a machine of the character described, the combination, with a counting device, operating mechanism to cause said counting device to record an item, indicating counters, and means to separately reset 110 to zero said counting device and said indicating counters, of a disk connected with the resetting means for said indicating counters and having a recess therein, a locking plate connected with said operating 115 mechanism, a pawl arranged normally in the path of said locking plate and having a lug, and an arm pivotally mounted on said machine and having a nose adapted to lie normally in the recess in said disk and be 120 moved out of said recess during the resetting of said counting devices, said arm also having a part adapted to be moved into the path of the lug on said pawl when said nose is moved out of the recess in said disk. 125

135. In an indicating device comprising a plurality of indicating counters, and means for positively actuating the units counter, of transfer mechanism comprising an escapement wheel connected with that 130

counter to which the count is to be transferred, a double-nosed pawl pivotally mounted adjacent to said escapement wheel, a spring to hold the forward nose of said pawl normally in engagement with said escapement wheel between the teeth thereof and to hold the other nose of said pawl normally out of the path of the teeth of said escapement wheel, whereby the rotation of 5 said escapement wheel will cause one of the teeth thereof to engage the forward nose of the pawl and thus move the rear nose of the pawl into the path of the approaching tooth, the relative length of the noses of 10 said pawl being such that the rear nose will be engaged by the approaching tooth before the pawl can move about its pivotal center when released by the forward pawl, thus 15 checking the movement of said escapement 20 wheel and the counter with which it is connected.

136. In a machine of the character described, an indicating counter, and means for resetting said indicating counter to zero, 25 of a drum having two indications arranged alternately about its periphery, and a connection between said drum and the resetting means for said indicating counter to cause the drum to be advanced one point each time 30 said indicating counter is reset to zero.

137. In a machine of the character described, an indicating counter, and means for resetting said indicating counter to zero, of a drum having two indications arranged 35 alternately about its periphery, and a connection between said drum and the resetting means for said indicating counter to cause the drum to be advanced one point each time 40 said indicating counter is reset to zero, and means to adjust said drum independently of said resetting means.

138. In a machine of the character described, the combination, with a counting device, operating mechanism therefor, means 45 for resetting said counting device to zero, a group of indicating counters, means for actuating said counters each time said operating mechanism is operated, and means for resetting said indicating counters to zero, 50 independently of said counting device, of a rotatable indicating drum having the words "In" and "Out" arranged alternately about the periphery thereof, and an operative connection between said indicating drum and 55 said resetting means for said indicating counter, whereby said drum is advanced one point upon each operation of said resetting means.

139. In a machine of the character described, the combination, with a counting device, operating mechanism therefor, means for resetting said counting device to zero, a group of indicating counters, means for actuating said counters each time said operating 60 mechanism is operated, and means for

resetting said indicating counters to zero independently of said counting device, of gears connected respectively with the resetting means for said indicating counter and with said drum, a shaft having gears 70 adapted to mesh with the respective first-mentioned gears, whereby movement will be imparted to said drum when said indicating counters are reset to zero.

140. In a machine of the character described, the combination, with a counting device, operating mechanism therefor, means for resetting said counting device to zero, a group of indicating counters, means for actuating said counters each time said operating mechanism is operated, and means for 80 resetting said indicating counters to zero independently of said counting device, of gears connected respectively with the resetting means for said indicating counter 85 and with said drum, a shaft having gears adapted to mesh with the respective first-mentioned gears, whereby movement will be imparted to said drum when said indicating counters are reset to zero, and means for 90 disconnecting one of the gears on said shaft from said shaft to permit said shaft to be rotated and said drum adjusted independently of said resetting means.

141. In a machine of the character described, the combination, with a group of indicating counters, means for resetting said counters to zero comprising a shaft, of an indicator drum, a gear connected with said drum, a shaft, a two-toothed gear carried by 100 said shaft and adapted to mesh with the gear on said drum, a second gear secured to said shaft, and a mutilated gear mounted on said resetting shaft and arranged to mesh with the last mentioned gear and rotate the same through a half revolution upon each full revolution of the resetting shaft, thereby causing said two-toothed gear 105 to advance the gear on said indicator drum one point.

142. In a machine of the character described, the combination, with a group of indicating counters, means for resetting said counters to zero comprising a shaft, of an indicator drum, a gear connected with said 115 drum, a shaft, a two-toothed gear carried by said shaft and adapted to mesh with the gear on said drum, a second gear secured to said shaft, and a mutilated gear mounted on said resetting shaft and arranged to mesh with the last-mentioned gear and rotate the same through a half revolution upon each full revolution of the resetting shaft, thereby causing said two-toothed gear to advance the gear on said indicator drum one point, 120 and means for disconnecting said shaft from the gear on said resetting shaft to permit the first-mentioned shaft to be rotated independently of said resetting shaft.

143. In a machine of the character de- 130

scribed, the combination, with a group of indicating counters, a resetting shaft for said counters, the rotation of which will return the several indicating counters to zero, of a collar mounted on said shaft and having a shoulder, an arm pivotally supported adjacent to said collar and having a nose adapted to be moved into and out of the path of said shoulder, a spring tending to move said nose away from said shoulder, a finger connected with said arm, and a part carried by said collar to engage said finger and move the nose of said arm into the path of said shoulder as said shaft approaches the completion of a revolution.

144. In a machine of the character described, the combination, with a group of indicating counters, a resetting shaft for said counters, the rotation of which will return the several indicating counters to zero, of a collar mounted on said shaft and having a recess and also having a projection arranged in advance of said recess, two arms pivotally mounted on a common axis, a resilient connection between said arms, one of said arms having a nose adapted to enter a re-

cess in said collar, a spring tending to move said nose away from said collar, and the other of said arms having a finger adapted to be engaged by the projection of said collar to move both arms about their common axis and cause the nose of the one arm to enter said recess.

145. In a machine of the character described, the combination, with printing counters, an electrotype plate arranged adjacent to said printing counters, having a blank space therein and having a recess adjacent to said blank space, of a type plate removably mounted in said recess with its type in position to fill in the blank space of said electrotype plate, means to retain said type plate in said recess, and means to print a record from said printing counters and said electrotype plate.

In testimony whereof, we affix our signatures in presence of two witnesses.

DAVID B. WHISTLER.
CHARLES W. RIPSCH.
